UNITED STATES PATENT OFFICE.

ARTHUR H. ADAMS, OF GALION, OHIO.

TELEPHONE-EXCHANGE SYSTEM.

Application filed May 13, 1920. Serial No. 381,128.

To all whom it may concern:

Be it known that I, ARTHUR H. ADAMS, a citizen of the United States, residing at Galion, in the county of Crawford and State of Ohio, have invented a certain new and useful Improvement in Telephone-Exchange Systems, of which the following is a specification.

This invention relates to telephone and other electrical signaling systems, and particularly to telephone systems in which machine switches are employed for establishing connections.

The principal object of the invention is to increase the efficiency of trunks and machine switches of telephone exchange systems.

For the purpose of analyzing the characteristics of this invention, it will be first explained how it affects the trunking and operation of any well-known telephone system.

Let us consider, for example, a telephone system having a capacity of ten thousand lines and in which machine switches are employed. Such switches are at present usually arranged to perform a primary movement to select a desired one out of a plurality of groups of lines, and a secondary movement to select or choose an idle one of the selected group of lines. However, it should be noted at the outset that the invention is not limited to systems or switches of any particular size, type or character.

At present, in such a telephone system, if each switch has a capacity of one hundred lines, first selectors, second selectors and connectors are necessary for establishing connections. The first and second selectors are interconnected by trunks bearing the various thousands numerical designations the trunks interconnecting the second selectors and connectors are differentiated from each other by the hundreds numerical digits of line numbers, and the connectors are connected direct with the subscribers' lines. A calling line may be connected to a called line only through trunks, the numerical designation of which corresponds in the thousands and hundreds digits to that of the called line. For example, called line No. 4692 may be reached only in the following manner:

A first selector selects one of a number of trunks numbered 4000 and is thereby connected with the second selector associated

with the selected trunk. Through this second selector, access may be had to all the lines the number of which is between 4000 and 4999. The second selector is then operated to select one of a number of trunks bearing the proper hundreds digit; that is to say, a trunk numbered 4600. This trunk leads to a connector in which terminate lines 4600-4699. By operating the connector in accordance with the tens and units digits of the called number (9 and 2), the called line is selected.

In order to select any one of the ten thousand lines, one first selector is necessary to select a certain one of ten trunks and an associated second selector, through which access may be had to the desired thousands group; each of ten second selectors must have access to trunks bearing the ten different hundreds designations within the thousands group of the second selector; and the one hundred connectors associated with these trunks must each be arranged to select the desired subscriber's line, the thousands and hundreds numerical designation of which has been determined by the selection of a particular second selector trunk and a particular connector trunk.

As is well known, one first selector, ten second selectors and one hundred connectors could not handle more than one connection within a thousands group or digit at a time. In order to take care of the usual traffic of a telephone system, the number of selectors and connectors, and thus the number of their interconnecting trunks, must be sufficient to handle a maximum number of simultaneous calls initiated in the exchange. That is to say, a plurality of trunks and second selectors must be provided through which access may be had to a certain thousands group of subscribers' lines, and a plurality of trunks and connectors must be provided to render accessible a certain group of one hundred subscribers' lines. For this reason, the first and second selectors are arranged to perform secondary movements to select or choose an idle one of the selected group of trunks.

The factors that determine the total number of selectors, connectors and associated trunks depend, first of all, on the probable number of simultaneous calls that will have to be established within the exchange. The number of such switches and trunks will be further dependent on the probable average

holding time of a trunk or selector, i. e., the probable time for which a trunk or switch will be held busy during the establishment of a connection; the probable number of calls that will be abandoned prior to the completion of the connection; etc. On the theory of probabilities, the total number of switches and trunks may be determined from the above mentioned and other conditions.

Assuming now that in calculating the traffic of the whole exchange, we decide that 600 second selectors and associated trunks and 540 connectors and associated trunks are necessary. These are the figures we obtain when considering the traffic of the telephone exchange as a whole, and their meaning is that a maximum of 540 simultaneous calls will be established in the exchange and, in addition to these, sixty calls will go only as far as the second selectors.

However, in some of the systems heretofore known, not the traffic of the telephone exchange as a whole, but the traffic of relatively small subdivisions of the telephone exchange must be considered in determining the total number of selectors and trunks. This is so, because only through certain selectors, connectors and associated trunks may access be had to certain subscribers' lines. It is possible to operate the systems of the prior art in a manner to permit the calling subscriber to appropriate any one of the first selectors for use because any called line may be reached through any first selector. But beyond the first selector, the traffic is definitely subdivided according to its destination. By operating the first selector to select a trunk and associated second selector bearing a certain numerical designation (e. g. 4000), the simultaneous calls directed towards the other nine groups of one thousand lines do not affect the calculations to determine the size of the group of trunks and associated group of second selectors through which access may be had to subscribers' lines 4000 to 4999. The probable number of simultaneous calls, average holding time and other factors that were considered in calculating the size of the second selector trunk groups, will vary in the ten groups. As above stated, if the traffic of the whole exchange is considered, then 600 second selector trunks are sufficient. However, the smaller the group the greater the deviation within the group from the average for the whole. In other words, the probability of (e. g.) 50% deviation from the average number of simultaneous calls into a particular thousands group is much greater than of a 50% deviation from the average number of simultaneous calls in the exchange as a whole. In flipping a coin, the average will be 50% tails and 50% heads. The larger the num-

ber of tosses, the closer we reach to the average, and vice versa. While 600 second selector trunks always will be sufficient for the whole exchange during a certain part of the day or season, group 1000 will need

only $\frac{600}{10} - a$; group 2000, $\frac{600}{10} + a$; group 4000, $\frac{600}{10} + b$; group 9000, $\frac{600}{10} - b$; etc., in-

stead of $\frac{600}{10}$ for each group. During other parts of the day or season, group 1000 will need $\frac{600}{10} + a + b$; group 2000, $\frac{600}{10} - c$; group 4000, $\frac{600}{10} - a - b$; group 9000, $\frac{600}{10} + c$, etc., second selectors. The probability is that in each one of the ten groups there will be a deviation from the average for the whole exchange, and it is impossible to predetermine in which group and when the deviation will take place upwards or downwards.

For these reasons, instead of the traffic of the exchange as a whole, the traffic towards each group of one thousand lines was taken into consideration in determining the size of each second selector trunk group, and thus the total number of second selectors. In any given group, during certain parts of the day this traffic will be larger, and during other parts of the day such traffic will be lower than $\frac{600}{10}$. Sufficient second selector trunks must be provided to permit access to the lines of each group during the busy as well as the idle periods of the day or month. Therefore, $\frac{600}{10}$ or $\frac{600}{10} - b$ trunks will not be sufficient

to take care of the traffic of a group. $\frac{600}{10} + b$

trunks must be provided for the 4000 group, $\frac{600}{10} + a$ second selector trunks for the 2000

group, etc., or $\frac{600}{10} + a + b$ trunks must be

provided for each group. If we count the second selectors and associated trunks that must be thus provided for handling the traffic of all the ten groups, we find that $600 + x$ are needed instead of 600, as would be the case if the traffic of the exchange as a whole could be considered.

The same considerations apply to the connector trunks. Here again, the traffic is subdivided, but in this case not only with respect to the traffic of the whole exchange or the traffic of the thousands group selected by the first selector. The second selector cannot select but a trunk of a certain thousands and hundreds numerical designation. Due to the variations within and between the various groups, the total number of con-

nectors and associated trunks will have to be $540 + x'$, instead of 540 as would be the case if the traffic of the whole exchange could be considered.

- 5 From the above it will be seen that, in the systems of the prior art, the number of trunks and associated selectors and connectors necessary for handling the probable traffic of an exchange is larger than is necessary for the handling of the traffic of the exchange as a whole. The total number of such trunks and selectors is dependent on the size of the trunk groups into which the traffic is subdivided, and this in turn depends on the capacity of the switching devices used. Notwithstanding the objections raised against switching devices having a capacity of more than one hundred lines, such large switches were considered economical under certain circumstances, mainly on account of the possibility of providing relatively large trunk groups, which results in a lesser subdivision of the traffic. In one hundred point switches, giving trunk groups of 10, it might be necessary under certain traffic conditions to provide more than ten trunks for access to a thousands group. One solution of such a situation would be to appropriate more than one group of ten trunks for access to the particular thousands group. In view of the fact that a group of such trunks could not be used for gaining access to more than one thousands group, waste of space and apparatus results from such arrangements. But even in this case the traffic was divided into relatively small groups.
- It has been suggested to employ so-called overflow trunks for the handling of the abnormal traffic. The provision of such arrangements is costly and leads to considerable complications in the system.

In accordance with the present invention, the number of the selectively operable switching devices, such as intermediate and final selectors and associated trunks, depends on the traffic requirements of the whole exchange, notwithstanding the fact that the capacity of the devices is relatively small. For instance, in calculating the number of second selectors and connectors and associated trunks to be provided, only the traffic conditions of the exchange as a whole need be considered, and the trunks, if arranged in accordance with the present invention, will be much more efficient than the necessarily larger number of trunks of a similar exchange, in which the traffic is subdivided into groups. Considering the above example, 600 second selectors and 540 connector trunks need only be provided in the present system.

Generally stated, the above-mentioned result is attained by routing a call through a trunk corresponding in numerical designation to certain digit or digits of the number

of the called line, if such trunk is available. If this trunk is busy, then the selector arranged in accordance with the present invention does not hunt for an idle trunk bearing the numerical designation corresponding to that of the called line, and thus limits to a particular group the accessibility of a line. The selector performs its hunting operation to select or choose an idle trunk within a certain range, irrespective of the numerical designation of the trunk. At another stage of the selective operations, means are actuated to compensate for the deviation of the selector from the desired numerical path and the connection is completed with the desired line.

The invention may be applied at any point of the selective stage. It is applicable to systems of all sizes, including multi-office systems, and in which selector switches of any well-known type are utilized. No attempt has been made to define the scope and the various features of the invention. This will be done in the appended claims. The above is merely introductory to the following general description of telephone systems in which the invention may be applied, and the detailed description of the circuits and apparatus of a telephone system embodying the invention.

In the drawings, Figs. 1, 2 and 3 represent as much of the circuits and apparatus of an automatic telephone exchange system as is necessary for a clear understanding of the details of a telephone system exemplifying the various features of the invention. Figs. 4, 5, 5^a, 6 and 6^a indicate a preferred scheme of numbering and wiring the terminal banks of first selectors, second selectors, and connectors.

General description.

Assuming a telephone system of the type considered in the above introduction, we find, for example, that, in view of all the traffic and operating conditions of the exchange as a whole, 540 first selectors, 600 second selectors and 540 connectors are needed. These figures will, of course, vary, depending on the particular local conditions and the factor of safety used in calculating.

Any well-known means, such as line switches, line finders, relays, or any other automatically or manually operated devices may be used for connecting the calling line with the wipers of any one of a plurality of the 540 first selectors. In accordance with the present embodiment of the invention, the first selectors are of the well-known type (see Patent No. 977,536 to C. H. North) that perform first a primary or rotary and then a secondary or vertical movement to engage with their wipers any one of the one hundred sets of terminals of which their respective banks are composed. There are three devia-

tions from the well-known structural arrangement of these selectors: (1) The terminal bank comprises ten horizontal, but eleven instead of ten vertical rows of contacts; 5 (2) the brush shaft may be moved twenty instead of ten vertical steps; and (3) each first and second selector is provided with two instead of one set of wipers. The two sets of wipers of each selector (144-147 and 10 144^a-147^a, Fig. 1) are multiplied together. The two sets of wipers are rigidly mounted on the brush shaft, the set of wipers 144^a-147^a being provided below the set 144-147 at a distance equivalent to the 15 distance covered by the brush shaft in moving by ten vertical steps. Furthermore, the lower wipers are displaced with respect to the upper wipers by one rotary step, whereby the former are always in line with the 20 vertical row of contacts immediately to the right of the vertical row of contacts with which wipers 144-147 are in alignment. Normally, the wipers 144-147 are one step to the left and one step below the first contact in the terminal bank (11XX, Fig. 4).

The numbering of the terminal bank, that is to say, the numbering of the trunks leading from the terminals of the first selector to the wipers of the various second selectors, 30 is illustrated in Fig. 4. In the present case, both the thousands and the hundreds digit of the called number is determined in the first selector. The tens and hundreds digits remain undetermined at this stage of the 35 selective operation, and for this reason, these digits are indicated by the letter "X." The first vertical row of terminals serves for reaching trunks 11XX, 12XX, 13XX, etc., 10XX; the second vertical row, for reaching 40 the trunks 21XX-20XX, etc.; and the tenth vertical row of terminals for reaching the trunks 01XX-00XX. It will be noted that the numbering is always from 1-0. The eleventh vertical row of terminals leads to 45 the same trunks as the first vertical row, these two rows being multiplied together.

In response to the thousands impulses sent out from the calling subscriber's station, the brush shaft is rotated in a right-hand direction by a corresponding number of steps. 50 Assuming that line #4692 is desired, the brush shaft of the first selector is rotated by four steps, bringing wipers 144-147 in line with vertical row IV, one step below terminal 41XX, and the wipers 144^a-147^a in line with vertical row V, eleven steps below terminal 51XX.

A change-over operation now takes place 60 in the circuits of the first selector, and in response to the hundreds digit 6-dialed by the subscriber, the brush shaft of the first selector is moved by six steps in a vertical direction. The wipers 144-147 pass over terminals 41XX, 42XX, etc., and in response 65 to the sixth vertical step are brought into

engagement with the terminals in which trunk #46XX terminates. The thousands and the hundreds digits of the number of this trunk correspond to those of the called number. The wipers 144^a-147^a are now 70 five steps below terminal 51XX.

The trunk 46XX is now tested for its busy or idle condition. If the trunk is idle, then it is immediately seized by the first selector, and the calling line is extended 75 through this trunk to the wipers of the second selector associated therewith. If the trunk is busy, then the first selector hunts in a vertical direction for an idle trunk.

Let us first assume that the trunk 46XX 80 is idle, and that the first selector seizes the trunk terminating therein. This trunk terminates in the wipers of a second selector, the mechanical construction of which is exactly the same as that of the first selector. The numbering of the terminal bank of this 85 second selector is shown in Fig. 5^a. It will be noted that the first terminal in the bank is 461X, and that the successive vertical rows, taken from left to right, comprise terminals numbered on a downward scale. Normally, the set of wipers 244-247 are one 90 step to the left and one step below terminal 461X, and the wipers 244^a-247^a, in line with vertical row 461X, eleven steps below terminal 461X.

In response to the seizure of the trunk terminating in the wipers of this selector, it is rotated by one step, bringing wipers 244-247 in line with vertical row I, one 100 step below terminal 461X, and wipers 244^a-247^a, in line with vertical row II, eleven steps below terminal 451X. The usual change-over operation takes place, and the second selector is ready to respond to the 105 tens impulses. The nine tens impulses cause the wipers to move in a vertical direction. Terminals 461X, 462X, etc., are successively passed, and in response to the ninth impulse, the wipers 244-247 rest in engagement with terminal 469X. The wipers 244^a-247^a are 110 now two steps below terminal 451X.

The trunk terminating in terminal 469X 115 is now tested, and assuming that it is idle, the trunk and the associated connector are seized. The connector bank comprises only ten rows of terminals, and the brush shaft carrying a single set of wipers is arranged to execute only ten vertical steps. Otherwise, the connector is of the same construction as the first and second selectors. The wipers 344-346 are normally one step to the left and one step below the first terminal in the bank. The numbering of this 120 terminal bank is shown in Fig. 6^a.

Immediately upon the seizure of this connector, its wipers are rotated by one step and are thus brought one step below terminal 4691. The connector is then ready to 125 respond to the units impulses (2), the 130

change-over operation taking place immediately upon its rotary displacement. Under the control of the units impulses, the connector wipers are moved in a vertical direction by two steps, and are arrested in engagement with the terminals 4692 in which the called line terminates. The ringing of the called party, the completion and restoration of the connection are then accomplished.

Let us assume now that neither the first nor the second selector finds idle the terminals of the first trunk encountered. In this case, when the first selector wipers 144-147 find the trunk terminals 46XX busy, the brush shaft is automatically caused to continue its vertical movement. The wipers 144-147 successively test the terminals 47XX, 48XX, 49XX, 40XX, and assuming that all these terminals test busy, the brush shaft is caused to move by a further step in a vertical direction. The wipers 144-147 now leave vertical row IV, and the wipers 144^a-147^a enter into engagement with terminal 51XX. If this terminal is busy, the vertical movement of the first selector is continued until the wipers 144^a-147^a encounter an idle set of terminals. Assuming that terminal 55XX is the first one idle, when the wipers encounter these terminals, the upward movement of the first selector is arrested, and the trunk terminating in these terminals is seized. It should be noted that the numerical designation of this trunk differs in both the thousands and the hundreds digits from that of the called line.

During this trunk-hunting operation of the first selector, a register associated therewith is caused to move its wiper 152 in a clockwise direction by as many steps as the first selector took in hunting for an idle trunk.

The second selector associated with the trunk #55XX is of the same mechanical construction as the second selector associated with the trunk 46XX. However, the numbering of the terminal bank is different. The numbering of this bank is shown in Fig. 5. Immediately upon the seizure of the trunk, the second selector is caused to move its brush shaft by one rotary step, whereby the upper brushes are positioned in line with vertical row I, one step below terminal 551X, and the lower wipers in line with vertical row II, eleven steps below terminal 541X. Due to the off-normal position of the register associated with the first selector, the change-over operation cannot take place in the circuits of the second selector. The brush shaft of the second selector is caused now to rotate step-by-step (with the upper wipers below horizontal row of terminals I) and simultaneously the register moves its wipers step-by-step

in a counter-clockwise direction. This operation continues until the register wiper reaches its normal position, when both the second selector and the register are arrested, and the change-over operation takes place in the circuits of the second selector.

The first selector took nine steps in hunt for an idle trunk. Therefore, the register was displaced by nine steps, and the second selector wipers were rotated by nine steps until the register wiper reached its normal position. For this reason, the upper wipers of the second selector are now positioned one step below the vertical row X, the numbering of which is the same as that of the I row in Fig 5^a.

Under the control of the tens impulses, the second selector wipers are now caused to travel in a vertical direction to engage terminal 469X. Thus, notwithstanding the fact that the first selector chose a trunk of a different numerical designation than the called line, the second selector was caused to re-route the call, and now the call is headed again towards the channel determined by the subscriber's calling dial.

If the trunk with which the wipers of the second selector now make contact is idle, the above-mentioned connector is seized, and the call completed in the usual manner. Assuming, however, that trunk 469X is busy, the second selector is automatically operated to hunt in a vertical direction for an idle trunk. First, the upper wipers of the selector engage terminals 460X and, finding these busy, the brush shaft is elevated by a further step, whereupon the upper wipers of the selector leave the terminals of vertical row X, and the lower wipers engage terminal 451X of row XI. The hunting operation continues until the lower wipers encounter a set of idle trunk terminals. Assuming that terminals 453X are the first idle ones in this row, the second selector is arrested with its wipers in engagement with these terminals, and seizes the trunk terminating therein.

During the trunk-hunting operation of the second selector, the register associated with the first selector was stepped in synchronism with the second selector. The second selector having taken four steps to reach an idle trunk, the wiper of the register was also displaced by four steps from its normal position.

The connector associated with trunk 453X is of the same mechanical and electrical arrangement as the one associated with trunk 469X; however, the terminal bank of this connector is wired in accordance with Fig. 6. Upon the seizure of the trunk, the connector wipers are brought below terminal 4551, but the register being off-normal, the change-over operation does not take place in the circuits. Under the control of

the register and simultaneously therewith, the connector wipers are caused to rotate. The register requiring four steps to be restored to normal, the connector wipers are 5 rotated by four steps. This will bring the wipers in line with vertical row V, which is the row containing the called line terminals. The change-over operation now takes place, and under the control of the units 10 impulses, the connector wipers are elevated by two steps and into engagement with the terminals of line #4692.

The call has reached its proper numerical destination, notwithstanding the fact that it 15 was routed through trunks provided for access to lines of a different thousands, hundreds and tens numerical designation. All this takes place without any additional act of the operator or subscriber.

20 A pilot switch is associated with each first and second selector for controlling its circuits. These pilot switches may be of any well-known design, e. g., like the one disclosed in Patent No. 988,390 to F. Schoen- 25 wolf. The pilot switches are equipped with three pairs of wipers, angularly displaced in a manner to permit one wiper of a pair to enter into co-operation with a row of terminals when the other wiper leaves the last terminal in the row.

30 The register is composed of a circular row of contacts, with which a wiper co-operates. The wiper may be moved in a clockwise or counter-clockwise direction under the control of suitably arranged magnets.

35 The terminal banks of all the first selectors are numbered in the manner indicated in Fig. 4. The system used in multiplying terminals of the first selectors depends on 40 the total number of second selectors. The terminal banks of one hundred second selectors accessible to one first selector are differently numbered, that is to say, in no two of such second selector banks will the trunk 45 bearing the same numerical designation appear in the same place. The principle followed in the numbering of the terminal bank of the second selectors is the same as the one followed in the terminal banks illustrated in 50 Figs. 5 and 5^a. The first terminal in the I vertical row of each one of the one hundred second selectors, accessible to one first selector, serves for a trunk of a different numerical designation. The other terminals in the I 55 horizontal row are numbered by the same thousands digit but gradually decreasing hundreds digits until the hundreds digit "I" is reached. After this comes the terminal of the trunk of the next lowest thousands 60 digit and the highest hundreds digit (0), and this is followed by the terminals of the trunks of the last mentioned thousands digit but gradually decreasing hundreds digits. The ten terminals within the same vertical 65 row are for trunks of the same thousands

and hundreds digit, but for different tens digits.

The one hundred different second selector numberings will be apparent from the following list, in which the first and last terminal in horizontal row I of each second selector is given:

1. 111X-011X	51. 611X-511X	75
2. 121X-021X	52. 621X-521X	
3. 131X-031X	53. 631X-531X	
4. 141X-041X	54. 641X-541X	
5. 151X-051X	55. 651X-551X	
6. 161X-061X	56. 661X-561X	
7. 171X-071X	57. 671X-571X	80
8. 181X-081X	58. 681X-581X	
9. 191X-091X	59. 691X-591X	
10. 101X-001X	60. 601X-501X	
11. 211X-111X	61. 711X-611X

32. 421X-321X	82. 921X-821X	105
33. 431X-331X	83. 931X-831X	
34. 441X-341X	84. 941X-841X	
35. 451X-351X	85. 951X-851X	
36. 461X-361X	86. 961X-861X	
37. 471X-371X	87. 971X-871X	110
38. 481X-381X	88. 981X-881X	
39. 491X-391X	89. 991X-891X	
40. 401X-301X	90. 901X-801X	
41. 511X-411X	91. 011X-911X	
42. 521X-421X	92. 021X-921X	115
43. 531X-431X	93. 031X-931X	
44. 541X-441X	94. 041X-941X	
45. 551X-451X	95. 051X-951X	
46. 561X-461X	96. 061X-961X	
47. 571X-471X	97. 071X-971X	120
48. 581X-481X	98. 081X-981X	
49. 591X-491X	99. 091X-991X	
50. 501X-401X	100. 001X-901X	

In the assumed case of a system in which six hundred second selectors are provided, one hundred selectors having differently numbered banks, the numbering of six second selectors will be the same but different from the other 594 second selectors. By dividing the total number of first selectors 130

(540) by the number of second selectors serving trunks in the same order (6), we obtain the number of the first selector banks that must be multiplied together. In the 5 present case, 90 first selector banks must be multiplied together.

A preferred method of multiplying is as follows: Of the 540 first selectors, the terminal 11XX of the first ninety will be multiplied together and connected to the wipers of a single one of the six second selectors, the banks of which are numbered like (1) of the above list. The terminal 11XX of first selectors 91-180 are multiplied together and connected to the wipers of the second one of the six second selectors numbered like (1). The wipers of the other four second selectors numbered like (1) are connected to the (multiplied) terminals 11XX of first selectors 181-270, 271-360, 361-450, and 451-540, respectively.

The trunking between the other first selector terminals and the second selector wipers is on the same principle, but the terminals of different groups of first selectors are preferably multiplied together. Terminals 12XX of first selectors 11-100 are multiplied together and connected to the wipers of one of the six second selectors belonging to group 2. The wipers of the other five second selectors belonging to this group are connected to the multiplied terminals, 12XX of first selectors 101-190, 191-280, 281-370, 371-460, and 461-540-10, respectively. The wipers of the six second selectors numbered like (3) are connected, respectively, to the multiplied terminals 13XX of first selectors 21-110, 111-200, 201-290, 291-380, 381-470, 471-20.

The above trunking arrangement may be readily followed out for all the selectors and the result will be that the terminals of dissimilar but overlapping groups of first selectors will be multiplied together. Other methods may be used in multiplying the first selector terminal banks. Terminal 12XX of three times ninety even number first selectors may be connected to three second selectors numbered like (2). The wipers of the other three second selectors of the same numbering may be connected to three times ninety odd number selectors.

In following out this last mentioned system of multiplying, terminals 13XX of first selectors 3, 6, 9 . . . 267, 270 are multiplied together and connected to the wipers of one second selector numbered like (3). Terminals 13XX of first selectors 273, 276 . . . 537, 540 will be connected in multiple to the wipers of another second selector like (3). Terminals 13XX of first selectors 2, 5, 8 . . . 266, 269 will be connected in multiple to a third one of the second selectors (3). Terminals 13XX of first selectors 272, 275 . . . 536, 539 will be multiplied to the fourth sec-

ond selector of group (3). Corresponding terminals of first selectors 1, 4, 7 . . . 265, 268 will be multiplied to the fifth second selector like (3), and terminals 13XX of first selectors 271, 274, 277 . . . 535, 538 to the 70 sixth second selector of this group. The other terminals will be multiplied by skipping 4, 5, 6, etc., first selectors.

Such merged multiplying of the first selector banks is particularly advantageous in 75 case, by some chance of the traffic or of the call distribution circuits, a group of first selectors might average busier than another. Where the call distribution to the first selectors is practically perfect, there is no advantage in such merging of dissimilar groups of trunks. As far as the present invention is concerned, it is wholly independent of the method of multiplying the first selector terminals. In the present case, for 80 instance, all the terminals of the first selectors may be wired in the same manner as the terminals 11XX, the number of first selectors being without any effect upon the number of second selectors and connectors. 85 As above stated, the number of the latter is calculated directly from the busy hour average simultaneous calls put up to them irrespective of the method of trunking the calls to the second selectors. 90

The second selectors have access to dissimilar but overlapping groups of trunks, and for this reason the probability of a first selector finding an idle second selector is greater than if the second selectors had access to entirely separate groups of trunks. Furthermore, due to the fact that the second selectors have access to trunks belonging to different numerical groups of trunks, the first selector also may be permitted to hunt 100 for a second selector of any one of a plurality of numerical groups. In some of the systems of the prior art, as soon as the first selector is operated in accordance with the thousands digit of the called number, it cannot hunt but for a second selector through which access may be had only to this same thousands group of lines. At this particular time, more than the average number of simultaneous calls may be directed towards 110 this particular group of thousand lines. To take care of this traffic, more than the average number of second selectors had to be provided for this group. In the present system, the first selector may extend a call in accordance with the thousands digit of the called number or in accordance with another thousands digit and still reach the line of the desired thousands designation. If excessive traffic is directed at this particular time towards the lines of the desired thousands digit, the first selector may select a trunk and associated second selector through which normally calls directed to another thousands group of lines pass. The prob- 120 125 130

abilities are that in no two groups will there be an abnormal traffic at the same time. Another advantage of the present method of arranging the trunks served by a selector resides in this; that, whereas in some of the systems of the prior art if all the terminals of a selector accessible during its secondary movement are not necessary for handling the traffic, the other terminals were useless; in the present system all the terminals accessible during a secondary movement are used irrespective of the number of trunks provided for the handling of the average traffic. Taking, for example, the so-called hundred point switch, one hundred sets of terminals had to be installed whether the traffic required one hundred or only sixty terminals. The other terminals were left to accumulate dust. With the present system of numbering, all the one hundred terminals may be used irrespective of the traffic requirements. One and the same terminal may be selected, once in response to a numerical operation of the selector, and at another time in response to a hunting operation of the selector. Due to this constant and probably uniform use of the terminals, the terminals will automatically be kept clean of dust and thus their electrical conductivity will not be impaired. In the systems of the prior art, not used or only seldom used, terminals must be constantly dusted by manual labor.

Similar advantages are attained by the use of second selectors and connectors arranged in accordance with the present invention. In this case the advantages are realized in connection with the hundreds instead of the thousands groups.

The terminal banks of all the connectors of the present system will be differently numbered. The numbering is on the same principle as the one used in Figs. 6 and 6^a. The following is a list of the first and last terminals in the horizontal row I of some of the one thousand connectors, (for the sake of clearness, the connectors are here divided into ten groups, A-J, of one hundred connectors):

omitted, a permanent busy guard is placed on the multiple wire. When the second selector wipers encounter such permanently bussed terminal, they will automatically 5 hunt for another terminal as though the terminal was rendered busy by another selector.

As above mentioned, the invention is not limited to selector and connector switches of the particular structure disclosed. For example, if the invention is applied with switches performing their primary motion in a vertical and their secondary motion in a horizontal direction, the wipers should be mounted on the brush shaft in such a manner that one set is in line with a horizontal row of terminals below the horizontal row with which the other set of wipers is in alignment, and enter into engagement with the first terminal of its row when the other set leaves the last terminal of the row with which it co-operates.

Various methods for embodying the invention into systems utilizing switches of the mentioned types, or switches that perform motions only in a rotary, only in a vertical or in two more planes will readily suggest themselves to those skilled in the art.

The present exemplification of the invention is so provided that a first or second selector can select only one out of ten idle trunks in extending a call. The limiting of the hunting movement of selectors to ten terminals has been found sufficient even in systems utilizing the usual grouped system of trunking, and will be more than sufficient in the present system. If, however, it is required to extend the hunting range of a selector, this may be readily accomplished by increasing the size of the terminal banks, changing the system of numbering in accordance with the principles herein disclosed, providing more than two sets of brushes to cooperate with the various rows of the terminal bank of a selector, etc. The invention is applicable to full automatic as well as automanual or semi-automatic systems.

The particular construction or arrangement of the pilot or "side" switches and register switch is immaterial and the two may be combined into one structure. Furthermore, the register may be provided elsewhere than in association with the first selector. For instance, in semi-automatic systems, the function of the register should be preferably accomplished by some means associated with the operator's impulse controlling mechanism or sender. Operators' revertive impulse senders used in conjunction with so-called power-driven systems are particularly adapted for taking care of this impulse registering operation.

Detailed description.

A subscriber at substation 100 (Fig. 1), desiring to obtain a connection with sub-

scriber's station #4692, removes his receiver from the switch-hook, closing an energizing circuit for his line relay 101. The line relay closes through its armatures circuits for the primary control apparatus disclosed in the mentioned patent to H. G. Webster, No. 1,252,974, patented January 8, 1918. Under the control of this apparatus, the relays 103 and 104 are energized to extend the calling line to an idle trunk leading to the "first selector." Upon the actuation of relays 103 and 104, a circuit is closed from ground through the winding of slow-acting relay 105, relay contacts 103^a and 104^a, the calling line circuit, the apparatus at the calling station, relay contacts 104^b and 103^b, and the winding of relay 112 to grounded battery. The relays 105 and 112 become energized. The relay 105 closes a circuit from ground through its armature and front contact, and then in parallel through resistances 103^c and 104^c, relay contacts 103^a and 104^a, the windings of relays 103 and 104 to grounded battery. Under the control of these circuits, the switching relays 103 and 104 are locked up. Another circuit closed upon the extension of the line to the first selector may be traced from grounded battery, through the winding of cut-off relay 102, relay contacts 104^c and 103^c, and the winding of relay 111 to ground. These relays become energized, and the closure of this circuit causes the changing of the electrical potential on the multiple calling terminals of the line in a manner to prevent its seizure. The relay 102 opens the circuit of relay 101, whereupon the primary control apparatus is actuated in a manner disclosed in the mentioned patent to H. G. Webster.

The energization of the relays 111 and 112 results in the closure of the following circuits: from ground through the right-hand armature and front contact of relay 111, the left-hand armature and front contact of the relay 112, and the winding of slow-to-energize relay 113 to grounded battery; from ground through the right-hand armature and front contact of relay 111, the right-hand armature and front contact of relay 112, the first contacts engaged by wipers 131^b and 131^a of arm 131 of the pilot switch, and the winding of the pilot switch magnet 130 to grounded battery. First the magnet 130 attracts its armatures, and after a short interval the relay 113 attracts its armature.

Thousands selection.

The subscriber proceeds now to operate his dial 100^a in accordance with the numerical designation of the called line. First, the thousands impulses are produced by interrupting the line circuit a number of times equivalent in numerical designation to the corresponding digit of the called

number. In the present case, four such impulses are produced. In response to each interruption of the circuit, the relay 112 releases its armatures, but the relay 105 being sluggish, maintains its armatures attracted during the sending of the impulses. Upon the first release of the armatures of relay 112, the relay 113 and the magnet 130 become de-energized. Upon the de-energization of magnet 130, the pilot switch arms 131, 132 and 133 are stepped by one step to cause their respective wipers to engage the second set of contacts. Upon the following closure of the line circuit, the relay 112 again attracts its armatures. These circuit closures during the sending of the impulses are of a relatively short duration, and the relay 113 is not traversed by current for a sufficient length of time to permit it to attract the retarded armature. However, the rotary magnet 141 is energized by the first short closure of the line circuit, the current path being traced from ground through the right-hand front contacts of relays 111 and 112, the #2 contacts co-operating with arm 131, wipers 131^a and 131^b, and the winding of magnet 141 to grounded battery. Upon the following (second) break of the line circuit and the consequent de-energizing of relay 112, the rotary magnet 141 becomes de-energized and moves wipers 144—147 and 144^a—147^a of the first selector by steps in a horizontal plane. The second inner contact of the bank served by pilot arm 131 is not connected to the winding of magnet 130. For this reason, the last mentioned and the subsequent operations of the relay 112 do not affect this magnet. Upon the second reclosure of the line circuit, the relay 112 again closes the circuit of magnet 141. Under the control of the following two circuit interruptions and closures, the relay 112 operates the magnet 141 over the above traced circuit, and this magnet rotates the wipers of the first selector by two additional steps. The fourth (last) interruption of the line circuit is followed by a relatively long closure of the circuit, permitting the energization of the relay 113. This relay closes a circuit from grounded battery through the winding of magnet 130, the armature and front contact of relay 113, the normally closed contacts of this magnet, and the #2 contacts engaged by wipers 132^a and 132^b to ground at the left-hand front contact and armature of relay 111. The magnet 130 becomes energized, interrupts its own circuit and causes thus the stepping of the pilot switch wipers into engagement with their respective third sets of contacts. When magnet 130 shifts wipers 131^a and ^b from the #2 contacts to the #3 contacts, the circuit to the magnet 141 is interrupt-

ed and this magnet becomes deenergized. The wipers 144—147 are moved by an additional step, the total number of steps corresponding to the thousands digit dialed. The wipers 144—147 are now below terminals 41XX (Fig. 4). As soon as pilot wipers 131 ^a and ^b engage the #3 terminals, the magnet 130 is again energized, the relay 112 being energized over the re-established line circuit. 75

Hundreds selection.

The calling subscriber produces now the six hundreds impulses. In response to the first interruption of the line circuit, the relay 112 is again de-energized, and by releasing its armatures, causes the de-energization of the relay 113 and the magnet 130. The magnet 130 moves the pilot switch wipers into engagement with the fourth set of contacts. The relay 113 remains de-energized during the sending of the hundreds impulses. Upon the subsequent closure of the line circuit, the relay 112 becomes energized and causes the energization of the vertical magnet 142, the circuit being closed from grounded battery through the winding of magnet 142, pilot wipers 131 ^a and ^b, and the right-hand armatures and front contacts of relays 112 and 111 to ground. 95

The second interruption of the line circuit results in the de-energization of the relay 112, whereupon the magnet 142 becomes de-energized and moves the wipers of the first selector one step in a vertical direction. 100 Upon the succeeding short closure of the line circuit, magnet 142 is again energized, and upon the third interruption of the circuit of relay 112, the magnet 142 is de-energized for the second time to lift the wipers to the second level. Relay 112 continues to control magnet 142 in accordance with the interruptions and closures of the line circuit. In response to the sixth opening of the line circuit, the magnet 142 lifts the wipers by the fifth step. Upon the relatively long closure of the line circuit following the sixth interruption, the relay 113 is again caused to attract its armature. 110

During the sending of the hundreds impulses, a relay 114 was maintained energized by current from ground through pilot wipers 132^a and 132^b, and the winding of relay 114 to grounded battery. Through its right-hand armature, the relay 114 closed an energizing circuit for relay 115. When the relay 113 becomes energized, it closes a circuit from grounded battery through the winding of magnet 130, the armature and front contact of relay 113, the normal contacts of 115 130, the left-hand armature and front contact of relay 114, and the pilot wipers 132 ^a and ^b to ground. The magnet 130 becomes energized and interrupts its own circuit, whereupon the pilot arms are moved with 125 130

their wipers into engagement with the #5 set of contacts. The wipers 131 *a* and *b* leaving the #4 contacts cause the de-energization of magnet 142. This magnet 5 moves the first selector wipers by a sixth vertical step into engagement with the terminals of trunk 46XX (Fig. 4). If the second selector to which this trunk leads is idle, then the trunk is immediately seized 10 for use. If, however, this trunk is busy, and this is the condition we will assume, the first selector hunts for an idle second selector trunk.

15 *Hunting for idle second selector.*

When the pilot arm 132 is moved out of engagement with the #4 set of contacts, the relay 114 becomes de-energized, but the slow-acting relay 115 retains its armatures 20 attracted for a brief period of time. If the selected trunk line is busy, then, as will be set forth in detail, the terminal with which the test wiper 146 of the first selector contacts is connected to ground. For this reason, a circuit is closed from ground through the wiper 146, the right-hand armature and back contact of the relay 114, the left-hand armature and front contact of relay 115, and the winding of relay 116 to grounded battery. The relay 116 becomes energized, and closes a locking circuit for itself through its right-hand armature and front contact and the test wiper 146.

The relay 115 becomes now de-energized. 35 A circuit is closed from grounded battery through the winding of the vertical magnet 142, the left-hand front contact and armature of the relay 116, the normal contacts 154 of the register magnet 150, wipers 132^b 40 and 132^a and the left-hand front contact and armature of relay 111 to ground. The magnet 142 becomes energized, and closes a circuit from ground through its armature and front contact, wipers 131^b and 131^a, and 45 the winding of register magnet 150 to grounded battery. The magnet 150 becomes energized, and by opening its contacts 154 causes the de-energization of the magnet 142. The wipers of the first selector are stepped 50 by one vertical step. Upon the opening of the contacts of the magnet 142, the magnet 150 becomes de-energized, closes contacts 154, and moves register wiper 152 into engagement with contact #1. If the contact engaged by the wiper 146 is grounded, indicating that the selected trunk is busy, the relay 116 is maintained energized, causing the repetition of the above described operation of magnets 142 and 150.

60 Assuming that all the trunks terminating in the No. IV vertical row (Fig. 4) are busy, the wipers 144-147 engage in succession contacts 46XX, 47XX, 48XX, 49XX, and 40XX. The contacts 40XX being busy, the wipers are moved by a fur-

ther step. The wipers 144-147 are now out of engagement with the IV vertical row of terminals, but the wipers 144^a-147^a engage terminals 51XX of row V. The locking circuit of relay 116 is controlled through 70 test wiper 146^a, and the hunting operation continues until the wiper 146^a encounters a non-grounded terminal.

Assuming that the first four terminals in row V are also busy and the terminals 55XX 75 are idle, when the latter are reached, the relay 116 becomes deenergized, preventing the further operation of magnets 142 and 150. The magnet 150 caused the movement of wiper 152 by as many steps as the wipers of the first selector took in hunting for an idle trunk. That is to say, the register wiper 152 is in engagement with contact #9.

A circuit is closed from ground through the left-hand armature and front contact of relay 111, the wipers 132^a and 132^b, contact 154 of magnet 150, the left-hand armature and back contact of relay 116, the right-hand inner armature and back contact of relay 115, the normally closed contact of magnet 130, the front contact and armature of relay 113, and the winding of magnet 130 to grounded battery. The magnet 130 becomes energized, and by interrupting its own circuit causes the stepping of the pilot switch arms into engagement with the sixth set of contacts. Ground is connected through vertical off-normal contact 123, the right-hand armatures and back contacts of relays 115 and 116, and wiper 146^a to the engaged test terminal and multiples thereof, guarding this trunk (#55XX) against seizure by another first selector. This ground is extended to the winding of relay 207 associated with trunk #55XX, causing the energization of this relay.

100 *Correcting operation.*

Upon the energization of the relay 207, first a circuit is closed from grounded battery through the winding of rotary magnet 241, the left-hand armature and back contact of relay 208, pilot wipers 231^a and 231^b, the right-hand armature and front contact of relay 207, and the right-hand rotary off-normal contacts 214 to ground. The magnet 241 becomes energized and closes an energizing circuit for relay 208. The latter attracts its armatures, opening the magnet circuit and closing a circuit for slow-to-release relay 209. The relay 209 becomes energized and remains in that condition during the subsequent vibration of the armature of relay 208. Upon the de-energization of magnet 241, the second selector wipers are rotated by one step and below terminals 551X, and the relay 208 is de-energized. The right-hand contact of rotary off-normal contacts 214 is opened, and the left hand contact closed. A circuit is now closed from 115 120 125 130

ground through the winding of magnet 151, wiper 152, the contact #9 engaged by this wiper, the right-hand outer armature and back contact of relay 116, wiper 147^a, the right-hand armature and front contact of the relay 207, the wipers 231^a and 231^b of pilot switch arm 231, the left-hand armature and back contact of relay 208, and the winding of rotary magnet 241 to grounded battery. The magnets 241 and 151 become energized. The rotary magnet 241 closes a circuit from ground through its front contact and armature, and the winding of relay 208 to grounded battery. The relay 208 becomes energized, and by opening the circuit of the magnets 241 and 151 causes its own de-energization. The magnet 241 moves the wipers of the second selector by a second step in a rotary direction, and the magnet 151 moves the wiper 152 of the register by one step in a counter-clockwise direction. Upon the de-energization of the relay 208, the mentioned circuit including magnets 151 and 241 is again closed, and the operation of these magnets is repeated, until, after being moved by nine steps, the register wiper 152 reaches its normal contact. The rotary magnet 241 of the second selector is thus caused to operate this selector first by one step and then by a number of steps equivalent to the number of steps by which the register wiper has been displaced (nine) in response to the hunting action of the first selector. The wipers of the second selector are now below terminals 461X (Fig. 5^a) corresponding in the thousands and hundreds digits with the number dialed by the calling party.

As soon as the second selector is displaced from its normal position and actuates the off-normal contacts 214, a circuit is closed from ground through these contacts, the pilot switch wipers 233^a and 233^b, the front contact and armature of the relay 209, and the winding of the pilot switch stepping magnet 230 to grounded battery. This magnet becomes energized. When the relay 209 becomes de-energized upon the permanent de-energization of the relay 208, the magnet 230 becomes deenergized and moves the arms 231, 232 and 233 by one step to cause the engagement by their wipers of the #2 sets of co-operating contacts. A circuit is now closed from ground through the right-hand armature and front contact of relay 111, the right-hand armature and front contact of relay 112, wipers 131^b—6 and 131^a—6, selector wiper 144^a, wipers 231^a—2 and 231^b—2, and the winding of magnet 230 to grounded battery. This magnet becomes energized.

Tens selection.

The calling party produces now nine impulses representing the tens digit of the called number. Upon the first interruption

of the line circuit, the relay 112 opens in its right-hand front contact the circuit of magnet 230, whereupon the pilot switch controlled by this magnet is moved into the third position. In its left-hand front contact, the relay 112 opens the circuit of the slow relay 113. This relay becomes de-energized and remains in that condition during the sending of the tens impulses. Upon the de-energization of relay 113, a circuit is closed from grounded battery through the winding of magnet 130, the armature and back contact of this relay, and the pilot wipers 132^a—6 and 132^b—6 to ground. The magnet 130 is energized. As soon as arm 232 reaches position 3, a circuit is closed from ground through the wipers 232^a—3 and 232^b—3, and the winding of relay 211 to grounded battery. Relay 211 becomes energized.

Upon the subsequent closure of the line circuit, the relay 112 connects ground through its right-hand armature and front contact, pilot switch wipers 131^a—6 and 131^b—6, selector wiper 144^a, pilot switch wipers 231^a—3 and 231^b—3, and the winding of vertical magnet 242 to grounded battery. The vertical magnet becomes energized, and closes a circuit from grounded battery through its lower armature and front contact, and the winding of relay 210 to ground. This relay becomes energized and closes a circuit from battery through its right-hand armature and front contact, and the winding of a slow relay 213 to ground at rotary off-normal contact 214. During the subsequent vibration of the armature of relay 210 under the control of the vertical magnet 242, the relay 213 maintains its armatures attracted. The magnet 230 is held energized through a circuit including the lower armature and front contact of relay 213.

Upon the second interruption of the line circuit, the magnet 242 is de-energized, and moves the wipers of the second selector by one step in a vertical direction. Under the control of the following eight impulses, the vertical magnet 242 elevates step by step the wipers of the second selector. In response to the last (ninth) interruption of the line circuit, the wipers 244—247 will have been elevated by eight steps. Upon the last long closure of the line circuit, the magnet 242 becomes energized and the relay 113 is permitted to attract its armature, whereupon the magnet 130 becomes de-energized and moves its associated pilot arms into position 7. The circuit of the vertical magnet 242 is now interrupted. This magnet becomes de-energized and causes the second selector wipers to take a ninth vertical step. The wipers of the second selector are now in engagement with the terminals of the trunk #469X. The relay 210 is now de-energized and causes the de-energization of relay 213. 130

This relay in turn opens the circuit of magnet 230, whereupon the pilot arms are moved into position 4.

Hunting for idle connector.

- 5 If the trunk with which the wipers of the second selector are now in engagement is busy, then ground is connected to its multiple test terminals. Assuming this to be the 10 case, the relay 211 does not become de-energized when the associated pilot switch moves out of position 3, because a locking circuit is closed through the right-hand inner front contact and armature of this relay, 15 the right-hand armature and back contact of relay 209, and the selector wiper 246. As soon as the pilot switch reaches position 4, a circuit is closed from grounded battery through the winding of vertical magnet 242, 20 the left-hand back contact and armature of the relay 210, the left-hand front contact and armature of relay 211, pilot wipers 231^b—4 and 231^a—4, and off-normal contact 214 to ground. The magnet 242 becomes 25 energized and closes two circuits; one from grounded battery through its lower armature and front contact, the winding of relay 210, to ground; and the other from ground through its upper front contact and armature, pilot wipers 232^b—4 and 232^a—4, wiper 145^a of the first selector, pilot wipers 131^a—7 and 131^b—7, and the winding of register magnet 150 to grounded battery. The magnet 150 and the relay 210 become energized. 30 In its left-hand back contact, the relay 210 opens the energizing circuit of the magnet 242, and in its right-hand front contact the relay closes an energizing circuit from grounded battery, through the winding of relay 213, and off-normal contact 214 to ground. Upon the de-energization of the 35 magnet 242, the relay 210 becomes de-energized and the wipers of the second selector are displaced by one step in a vertical direction. In its upper front contact, the magnet 242 opens the energizing circuit of the magnet 150, whereupon this magnet becomes de-energized, and moves the register wiper 152 into engagement with its #1 contact. Upon the energization of the relay 40 213, a circuit is closed from grounded battery through the winding of magnet 230 and the lower armature and front contact of relay 213 to ground. This magnet becomes 45 energized. As above stated, during the vibration of the armature of relay 210, the relay 213 maintains its armatures attracted. 50 If the trunk with which the selector wipers are now in engagement is busy, the locking circuit traced through wiper 246 maintains the relay 211 energized. For this reason, the circuit of magnet 242 is 55 again closed, resulting in the repetition of the above described operations for moving 60 the wipers of the second selector and the 65 wiper of the register from one set of contacts to the next, until the selector finds an idle trunk. The first trunk terminal engaged by wiper 246 after it leaves terminal #469X is #460X (Fig. 5). In response to 70 the second vertical step taken by the wipers, the wipers 244—247 leave the #X vertical row of terminals and the wipers 244^a—247^a begin to hunt through the #X1 vertical row of terminals. Assuming that three additional steps are taken before an idle trunk terminal is reached, when the wiper 246^a 75 encounters the test terminal of an idle trunk #453X, the relay 211 becomes deenergized and causes the opening of the circuits of 80 magnet 242 and relay 210. Shortly after the de-energization of relay 210, the relay 213 becomes de-energized. Upon the de-energization of relay 213, the magnet 230 becomes de-energized and moves the associated pilot arms into position 5. The 85 second selector having taken four steps to reach an idle connector trunk, the register wiper 152 will be in engagement with terminal #4. 90
- The relay 211 closes a circuit from ground through its right-hand inner armature and back contact, the right-hand back contact and armature of relay 209, wiper 246^a, and the winding of relay 312 associated with 95 trunk #453X to grounded battery, for energizing this relay. This ground being applied to the multiples of the test terminal of this trunk, the seizure of the trunk by another second selector is prevented. The 100 connector wipers are now rotated one step. A circuit is closed from grounded battery through the winding of rotary magnet 341, left-hand contacts of relay 313, rotary off-normal springs 320, and the inner right-hand contacts of relay 312 to ground. Magnet 341 closes an energizing circuit for relay 313 and the latter opens the circuit of magnet 341. Upon the de-energization of magnet 341, the relay 313 becomes de-energized. 105 The connector cannot be further rotated under the control of this circuit because of the opening of contacts 320 upon the rotary displacement of the connector. The connector wipers are now below the terminals 110 of line #4531 (Fig. 6).
- Upon the energization of the relay 313, the relay 314 becomes energized. This relay is of the slow-to-release type and maintains its armatures attracted for a short 115 period of time after the de-energization of relay 313. Before the relay 314 had time to release its armatures, a circuit is closed from grounded battery through the winding of magnet 341, the left-hand back contact 120 and armature of relay 313, the left-hand armature and front contact of relay 314, vertical off-normal contact 321, second selector wiper 247^a, the right-hand outer back contact and armature of the relay 125 130

211, the right-hand armature and front contact of relay 207, first selector wiper 147^a, the outer right-hand contact and armature of relay 116, the contact #4 of the register, 5 wiper 152, and the winding of magnet 151 to ground. The magnets 151 and 341 become energized. The magnet 341 closes a circuit from ground through its armature and front contact, and the winding of relay 10 313 to grounded battery. This relay becomes energized and again closes the circuit for slow-to-release relay 314 to maintain it energized. In its left-hand back contact, the relay 313 opens the circuit of magnets 15 151 and 341, and these magnets cause, respectively, the displacement of register wiper 152 by one step in a counter-clockwise direction, and the displacement of the connector wipers by a second step in a rotary 20 direction. The relay 313 is again energized and this operation continues until the register wiper 152 reaches its normal position, the connector being rotated by as many steps (four) as is required to restore to normal 25 the register. While the relay 313 is vibrating its armatures under the control of magnet 341, the slow-acting relay 314 maintains its armatures attracted. When the register wiper 152 reaches its normal position, the 30 circuit of magnets 151 and 341 is permanently opened and the relay 313 becomes de-energized. Relay 314 is now de-energized. The connector wipers, having successively engaged terminals of lines Nos. 35 4521, 4511, 4601, are now in engagement with the terminals of line No. 4691 (Fig. 6).

Sending of the units impulses.

The calling subscriber proceeds now to 40 send the two units impulses. The relay 112 vibrates its armatures in response to the interruptions and closures of the line circuit. Upon the first de-energization of this relay, the relay 113 becomes de-energized 45 and remains in that condition during the sending of the impulses. Magnet 130 is also de-energized by the opening of the right-hand contact of relay 112. This magnet was energized as soon as the pilot switch 50 reached position 7, by current flowing from grounded battery through the winding 130, pilot wipers 132^a—7 and 132^b—7 and the right-hand front contacts and armatures of relays 112 and 111 to ground. The pilot 55 switch now shifts its wipers to the 8th position. An energizing circuit is closed for magnet 130 from ground through the left-hand inner armature and front contact of relay 111, the pilot wipers 132^a and b—8, the 60 back contact of relay 113, and the winding of magnet 130 to grounded battery.

Upon the subsequent closure of the line circuit, the relay 112 becomes energized and closes a circuit that may be traced from 65 ground through the right-hand armatures

and front contacts of relays 111, 112, pilot wipers 131^b—8 and 131^a—8, first selector wiper 144^a, the upper back contact and armature of the relay 213, second selector wiper 244^a, the left-hand contact of relay 70 312, rotary off-normal contact 322, the right-hand armature and back contact of relay 314, and the winding of magnet 342 to grounded battery. This magnet becomes energized and closes through its armature 75 and front contact an energizing circuit for relay 315. Upon the subsequent interruption of the line circuit, the magnet 342 becomes de-energized under the control of the relay 112, and moves the connector 80 wipers by one step in a vertical direction.

Upon the following last closure of the line circuit, the relay 112 becomes permanently energized. The magnet 342 is again energized, and somewhat later, the slow-to-pull-up relay 113 becomes energized. In its back contact, the relay 113 opens the circuit of magnet 130, whereupon the latter becomes deenergized and permits the pilot arms to escape into the ninth position.

When the pilot wipers 131^a and b leave their eighth contact, the above-traced circuit for magnet 342 is opened in these contacts. The magnet 342 becomes deenergized and moves the connector wipers by a second step in the vertical direction. The connector wipers are now in engagement with the terminals of line No. 4692. The relay 315 releases its armatures shortly after the last deenergization of magnet 342.

If the called line is idle, then, as will be set forth more in detail, full battery potential exists on its test terminal, permitting the energization of marginal test relay 316 through the following path: grounded battery 101 through the winding of the cut-off relay 102^a of the called line, test terminal and connector test wiper 346, the right-hand back contact and armature of relay 315, the high resistance left-hand winding of the relay 316, and vertical off-normal contact 325 to ground. The relays 102^a and 316 become energized. The relay 316 locks up through its low resistance right-hand winding, outer right-hand armature and front contact and the above-traced circuit through the winding of the cut-off relay. Due to the closure of this path, the electrical potential on the multiples of the test terminal is reduced so as to prevent the energization of another test 115 relay like 316 in response to its connection with this line by its associated connector switch. The relay 316 closes a circuit through its right-hand outer armature and front contact for energizing relay 318, and a 120 circuit from ground through interrupter 333, its inner-right-hand armature and front contact, the lower back contact and armature of relay 330, and the winding of relay 332 to grounded battery. This relay is 125 130

periodically energized and deenergized, and through its front contacts applies ringing current to the called line from a source 384.

When the called subscriber responds by 5 removing his receiver from the hook, the relay 330 becomes energized by current flowing through a circuit including the right-hand and left-hand outer armatures and front contacts of relay 318, impedance 10 coil 331, the back contacts and armatures of relay 332, and the called line circuit. Upon the energization of the relay 330, the circuit of relay 332 is permanently opened, and the talking connection between the calling 15 and called subscribers is completed in the upper armatures and front contacts of this relay. A circuit is now closed from grounded battery through the winding of relay 329, the uppermost armature and front 20 contact of relay 330, the right-hand outer armature and front contact of relay 312, and the left-hand inner front contact and armature of relay 318 to ground. The relay 329 becomes energized, and closes a 25 locking circuit for itself through its right-hand armature and front contact, and the left-hand outer front contact and armature of relay 318.

30 *Severing of connection.*

When disconnection is desired, and the calling and called parties restore their receivers, the relays 105, 112 and 330 become deenergized. The relay 105 opens the holding 35 circuits of relays 103 and 104, and these relays in turn open the circuits of relays 102 and 111. Relay 112 opens the circuit of relay 113. The relay 111 closes a circuit from ground through its left-hand inner armature and back contact, contacts 133a and b—9, the normally closed register contact 154, the normal contact of magnet 130, the left hand outer armature and back contact of relay 111, the back contact and armature 40 of relay 113, and winding of magnet 130 to grounded battery. This magnet interrupts its own circuit and permits the escape of the pilot switch wipers to normal (No. 1 contact). A circuit is now closed from ground 45 through the rotary off-normal contacts 109, pilot contacts 133^a—1 and 133^b—1, and the winding of release magnet 143 to grounded battery. The first selector switch is restored to normal, whereupon the circuit of magnet 50 143 is interrupted in contacts 109. Upon the deenergization of relay 112, the relay 113 becomes deenergized.

Upon the removal of the selector wiper 146^a from the terminal engaged by it, the 55 relay 207 becomes deenergized and closes a circuit from ground through rotary off-normal contact 214, the left-hand outer armature and back contact of relay 207, pilot wipers 233^a—5 and 233^b—5 and the winding 60 of release magnet 243 to grounded battery.

This magnet restores the second selector to normal. While the release magnet is energized, the pilot magnet 230 is maintained energized by a circuit including the armature and front contact of magnet 243. When 70 the release circuit is opened in contact 214 upon the restoration of the second selector, the magnet 243 becomes deenergized and causes in turn the deenergization of magnet 230. The latter allows the pilot switch arms 75 to return to normal position.

Upon the restoration of the second selector, the relay 312 becomes deenergized. When the called subscriber restores his receiver and the relay 330 becomes deenergized, a circuit is closed from ground, through the left-hand outer armature and front contact of relay 318, the right-hand front contact and armature of relay 329, the uppermost armature and back contact of relay 330, the left-hand front contact of 80 329, rotary off-normal contact 324, and the winding of release magnet 343 to ground. This magnet causes the restoration to normal of the connector switch, whereupon its circuit 85 is interrupted in contacts 324. The relays 102^a and 316 become deenergized, causing in turn the deenergization of relays 318 and 329.

While the second selector is being released, 90 its seizure is prevented by the application of a busy ground to its test terminal through the front contact of relay 205. This relay may be energized over a circuit including rotary off-normal contacts 206 and 214, and 95 the left-hand inner armature and back contact of relay 207.

95 *Premature disconnection.*

If at any time in the course of the establishment of a connection, the calling subscriber decides to abandon the call, then, upon the hanging up of the receiver at the calling station, the relay 111 becomes deenergized and closes an energizing circuit for 100 magnet 130 through the pilot wipers 133^a and b, and the normally closed contacts of 105 154. This circuit may be closed in positions 2—9 of the pilot switch. The magnet 130 by interrupting its own circuit causes the 110 stepping of the pilot wipers until position 1 is reached, whereupon the restoration proceeds in the above-described manner.

If the premature disconnection occurs in 115 position 2 of the pilot switch associated with the second selector, then, upon the deenergization of relay 112, the circuit of magnet 230 is interrupted and this magnet permits the escapement of its pilot switch into position 3. From position 3, the pilot switch is 120 moved into position 5 under the control of a circuit extending from grounded battery, through the winding and self-interrupting contact of magnet 230, the left-hand outer armature and back contact of relay 207, and 125 130

the left-hand contact of 214 to ground. In position 5 of the switch the magnet 243 becomes energized and locks up in turn the magnet 230 until the second selector is released to normal. Magnets 243 and 230 become deenergized and the pilot wipers are moved into position 1.

If the calling party hangs up when the pilot switch of the second selector is in position 3, then upon the deenergization of the relay 112, the magnet 242 becomes deenergized, opens the circuit of relay 210 and this relay in turn causes the deenergization of relay 213. The holding circuit of magnet 230 is now opened in the front contact of relay 213 and the pilot switch is permitted to escape to position 4. When the relay 207 is deenergized in response to the restoration of the first selector, a circuit is closed from ground through the off-normal contacts 214, the left-hand armature and back contact of relay 207, the back contact, armature, and winding of magnet 230 to grounded battery. The magnet 230 interrupts its own circuit and moves the pilot wipers into position 5. From this point on the restoration of the second selector and associated apparatus proceeds in the same manner as in response to the severing of an already established connection.

If the calling party prematurely restores his receiver while the register is in an off-normal position, then the return to normal of the register is insured by a slow-acting relay 155 associated therewith. This relay is energized through a circuit including its left-hand armature and back contact, the upper contact of 154, closed by cam 153 while wiper 152 is in an off-normal position, pilot wipers 133 *a* and *b*, and the back contact and armature of relay 111. Through its right-hand front contact, the relay 155 operates magnet 151 to return to normal the register.

45 *Attempted seizure of a busy line.*

If the called subscriber's line is busy, then, after the operation of the connector in accordance with the units impulses, the test relay 316 does not receive sufficient current to pull up its armatures. For this reason, no ringing current is sent to the called station, and when relay 315 becomes deenergized, a circuit is closed from a busy tone machine 350, through vertical off-normal contact 323, the outer left-hand back contact and armature of relay 315, the left-hand back contact and armature of relay 316, the left-hand armature and front contact of relay 312, second selector wiper 244^a, the upper armature and back contact of relay 213, first selector wiper 144^a to the calling subscriber's receiver, to inform him of the busy condition of the line.

65 When the calling party hangs up his re-

ceiver and causes the restoration of the first and second selector switches, the relay 312 becomes deenergized and closes a circuit from ground through its right-hand inner armature and back contact, the left-hand armature and back contact of relay 329, rotary off-normal contact 324, and the winding of magnet 343 to grounded battery. The magnet 343 becomes energized, and causes the restoration of the connector switch. The restoration of the first and second selectors takes place in response to the hanging up of the receiver at the calling station.

The term "overlapping" as applied to groups (of telephone lines, trunks, sub-station, etc.) in the claims is hereby defined as meaning that groups so designated are so arranged that a number, less than all, of the lines of one group are identical with lines that appear in or form part of another group. Two trunk lines or two groups of trunk lines have access to overlapping groups when through the one trunk line or the one group of trunk lines ultimate access is had to a group of lines overlapping the group of lines to which the other trunk line or group of trunk lines give access.

"Identical" as used in the claims does not necessarily mean that the lines have the same numerical designation in two groups. It means only physical identity or electrical continuity.

What I claim is:

1. In an automatic telephone switching system, selecting and selectable contacts, the latter being variously identified with routings to different line groups, and means by which such selectable contacts may be used for extending calls to particular groups regardless of the group identification of the contacts.

2. In a telephone exchange system, a plurality of lines, a selector switch, and contacts for said switch successively giving access to groups of lines such that the two groups of lines accessible through two successive ones of said contacts,—taking said contacts in the order of their selection by said selector switch,—shall each comprise lines common to both groups and also other lines.

3. In a telephone exchange system, a plurality of lines, a selector, and contacts for said selector successively giving access to groups of lines which groups overlap in identity.

4. In a telephone exchange system, a plurality of lines, a selecting means, two contacts in said means giving access to two different groups of said lines, said groups having at least one of said lines in common.

5. In a telephone exchange system, a plurality of lines each bearing a different numerical designation, three trunks through

- which calling and called lines may be interconnected, two selector switches, means for actuating one of said switches in accordance with the designation of called lines to co-operate with two of said trunks, and means for operating the other switch in accordance with the designation of called lines to co-operate with one of the mentioned two trunks and the third trunk.
6. In a telephone exchange system, a plurality of lines each designated differently from the other, one hundred and ten trunks through which calling and called lines may be interconnected, two selector switches, means for actuating one of said switches in accordance with the designation of called lines to co-operate with one hundred of said trunks, and means for operating the other switch in accordance with the designation of called lines to co-operate with ninety of said one hundred trunks and the ten other trunks.
7. In a telephone exchange system, a plurality of lines each designated differently from the other, a first, a second, a third and a fourth trunk through which calling and called lines may be interconnected, three selector switches, means for operating one of said switches in accordance with the numerical designation of called lines to co-operate with the first and second trunk, means for operating another of said switches in accordance with the designation of called lines to co-operate with the second and third trunk, and means for operating the third switch in accordance with the designation of called lines to co-operate with the third and fourth trunk.
8. In a telephone exchange system, a plurality of differently designated telephone lines, a switching device, means for operating said device in accordance with sets of numerical impulses, means for rendering busy said lines, and means for operating said device to choose an idle one of said differently designated lines in response to one or to a very different set of impulses.
9. In a telephone exchange system, a plurality of differently designated lines, a plurality of correspondingly designated trunks, a plurality of switching devices, means for operating said devices in accordance with the designation of the called line, means including said devices for rendering busy said trunks, and means for operating said devices to choose an idle one of said trunks in connecting a calling line with a certain called line.
10. In a telephone exchange system, a plurality of differently numbered lines, a field of trunk terminals each numbered according to the lines therethrough accessible and all differently numbered, moving means to select a desired terminal in said field, means for rendering busy said terminals,
- and means responsive to the busy condition of a desired terminal for operating said moving means to select successively in said field of differently numbered terminals until an idle one is found.
11. In a telephone exchange system, two groups of differently designated lines, a selector switch for interconnecting lines of said groups, means for rendering busy said lines, contacts for said lines arranged in groups on said selector, means operable in accordance with the designation of the called line for causing said selector to select a group of contacts, means operable in accordance with the designation of the called line for causing said selector to select in one plane a certain contact in the selected group, and automatic means actuated thereupon for operating said selector to hunt in the said plane for an idle one of a certain predetermined number of line contacts.
12. In a telephone exchange system, a plurality of differently designated lines, a selector switch for connecting with said lines, means for rendering busy said lines, contacts for said lines arranged in groups on said selector, means operable in accordance with the designation of the called line for causing said selector to select in one plane a group of contacts, means operable in accordance with the designation of the called lines for causing said selector to select in another plane a certain contact in the selected group, and automatic means actuated thereupon for operating said selector to hunt in said other plane for an idle one of a certain predetermined number of line contacts.
13. In a telephone exchange system, a plurality of differently designated lines, means including a plurality of trunks and a selector switch for interconnecting said lines, less than one hundred and eleven trunk terminals divided into rows of ten on said selector, means for rendering busy said trunk terminals, means for operating said selector in accordance with the designation of the called line to select a row of terminals, means for operating the selector in accordance with the designation of the said called line for selecting a certain terminal in the selected row, and automatic means actuated thereupon for operating said selector to choose an idle one of ten trunk terminals.
14. In a telephone exchange system, a plurality of lines designated by different combinations of digits, a plurality of trunks, each designated by certain digits, means for producing impulses representing the various digits, and means responsive to the operation of said last-mentioned means for connecting a calling line with a certain called line through any one of said trunks.
15. In a telephone exchange system, a

- plurality of main groups of subscribers' lines, said main groups differing successively by one sub-group, a selective device, means to connect said selective device to a calling line, a plurality of trunks successively accessible to said selective device and each giving access to a different successive main group of subscribers' lines, means to operate said selective device in accordance with the number of the called line to select the one trunk giving access to that one of said main group of lines having the called line in its first sub-group, and means cooperating with said selective device to test said one trunk and, if busy, to test succeeding trunks until an idle one is found giving access to a main group of lines containing the called line in another than the first sub-group.
16. In a telephone exchange system, a plurality of lines, each bearing a different numerical designation, means for performing a number of numerical selective operations, means responsive to the performance of selective operations the numerical value of which corresponds to that of the numerical designation of the called line for establishing a connection with the particular called line, and means responsive to the performance of selective operations the numerical value of which is different from that of the called line for establishing the said connection.
17. In a telephone exchange system, a called line designated by a number composed of a plurality of digits, means for performing a plurality of selective operations in accordance with said digits to select said called line, and means for performing selective operations in accordance with other digits for selecting the said called line.
18. In a telephone exchange system, a called line designated by a number composed of two digits, means for performing two selective operations in accordance with other digits than the ones of the line number, and means operative thereupon for establishing a connection to said called line.
19. In a telephone exchange system, a called line designated by a number consisting of two digits, means for performing a selective operation in accordance with one of said digits, means for performing another selective operation in accordance with another digit than the second digit, and means responsive to the performance of the said two selective operations for establishing a connection with the said called line.
20. In a telephone exchange system, a called line designated by a number composed of a plurality of digits, means for performing a plurality of selective operations in accordance with some digits of the called line, means for performing selective operations in accordance with other digits than the remainder of the digits of the called

line number, and means responsive to the performance of all the said selective operations for establishing a connection with the called line.

21. In a telephone exchange system, a plurality of lines designated by numerals composed of a plurality of digits, a plurality of groups of trunks, each group representing a certain numerical digit, a plurality of selector switches, means for operating said switches in accordance with the numerical designation of a called line, means operative thereupon for establishing a connection with the called line through a trunk of each group, the added numerical value of said trunks being equivalent to that of the called number, means for rendering busy said trunks, and means responsive to the busy condition of trunks for establishing a connection to the said called line through one trunk of each group, the added numerical value of such trunks being different from that of the called number.

22. In a telephone exchange system, a plurality of numerical trunks, means for seizing said trunks in the normal establishment of connections, and means for seizing said trunks as overflow trunks.

23. In a telephone exchange system, a plurality of differently designated lines, a plurality of correspondingly designated trunks, a selector switch, contacts for said trunks arranged in a plurality of groups on the selector switch, means for operating said selector in accordance with the designation of the called line to select a correspondingly designated group of contacts, means for rendering busy said trunks, and means for operating said selector to hunt for an idle trunk contact in the said correspondingly designated group and in another group as the overflow group of the former.

24. In a telephone exchange system, a plurality of lines, means including a selectively operable switching device for interconnecting two of said lines, a plurality of sets of stationary contacts for said device, a co-operating set of movable contacts for said device, means for operating said movable contacts to perform primary and secondary movements, means for arresting said movable contacts on a certain set of stationary contacts in response to a primary movement, and means for arresting the said movable contacts on the said stationary contacts in response to a secondary movement.

25. In a telephone exchange system, a group of differently designated lines, means including another group of lines and a selector switch for interconnecting calling and called lines of said group through a line of the other group, a plurality of rows of contacts for the lines of said other group on said selector, means for operating said selector in accordance with the designation of

- the called line to select a certain row of terminals, means for operating the selector in accordance with the designation of the said called line for selecting a certain terminal in the selected row, means for rendering busy the contacts of the lines, and automatic means for operating said selector for choosing an idle trunk terminal in the said selected row and another row.
26. In a telephone exchange system, a group of differently designated lines, means including another group of lines and a selector switch for interconnecting calling and called lines of said group through a line of the other group, a plurality of rows of contacts for the lines of said other group on said selector, means for operating said selector in one plane in accordance with the designation of the called line to select a certain row of contacts, means for operating the selector in another plane in accordance with the designation of the said called line for selecting a certain contact in the selected row, means for rendering busy the contacts of the lines, and automatic means for operating said selector in the said other plane for choosing an idle contact in the said selected row and another row.
27. In a telephone exchange system a plurality of lines, means including a selectively operable switching device for interconnecting said lines, a plurality of rows of stationary contacts for said device, a plurality of movable contacts, means for operatively engaging any one of said rows of stationary contacts by any one of said movable contacts, and means for connecting a calling line with a certain called line through any one of said movable contacts.
28. In a telephone exchange system, a plurality of numerically designated lines, means including a selectively operable switching device and a plurality of numerically designated trunks for interconnecting said lines, a plurality of rows of stationary contacts for said device in which said trunks terminate, a plurality of movable contacts, means for operatively engaging any one of said rows of stationary contacts by any one of said movable contacts, means for operating said movable contacts in accordance with the numerical designation of a called line, and means for connecting a calling line with a certain called line through any one of said movable contacts and a stationary contact in any one of said rows.
29. In a telephone exchange system, a plurality of lines, means including a selector switch for interconnecting said lines, a plurality of rows of stationary contacts for said switch, a brush shaft for said switch carrying two sets of radially displaced wipers cooperating with said stationary contacts, means for operating said shaft in accordance with the numerical designation of the called line, and means for connecting a calling line with a certain called line through any one of said sets of wipers and any one of a plurality of rows of stationary contacts.
30. In a telephone exchange system, a plurality of lines, means including a selector switch for interconnecting said lines, a plurality of rows of stationary contacts for said switch, a brush shaft for said switch carrying two sets of axially displaced wipers cooperating with said stationary contacts, means for operating said shaft in accordance with the numerical designation of the called line, and means responsive to the last mentioned operation for connecting a calling line with a certain called line through any one of said sets of wipers and any one of a plurality of rows of stationary contacts.
31. In a telephone exchange system, a plurality of lines, means including a selector switch for interconnecting said lines, a plurality of rows of stationary contacts for said switch, a brush shaft for said switch carrying two sets of radially and axially displaced wipers, each of said wipers being always in operative relation with another row of stationary contacts than the other, means for operating said shaft in accordance with the numerical designation of the called line, and means for connecting a calling line with a certain called line through any one of said sets of wipers and any one of a plurality of rows of stationary contacts.
32. In a telephone exchange system, a selector switch, two sets of wipers for said selector switch, rows of fixed contacts in said selector switch, means for rendering busy said contacts, means for operating one of said wipers to test all the contacts in any one of said rows, and means operative thereupon for causing the other set of wipers to test the contacts of another row.
33. In a telephone exchange system, a plurality of lines designated by numerals comprising different tens and units digits, a connector switch for selecting any one of said lines, an impulse device for controlling impulses representing tens and units digits of lines, and means for operating said connector under the control of said impulse device only in accordance with the impulses representing the units digits.
34. In a telephone exchange system, a plurality of lines designated by numerals representing different tens and units digits, a connector switch, means for operating said connector in two planes to select any one of said lines, an impulse device for controlling impulses representing tens and units digits of lines, and means for operating said connector under the control of said impulse device only in accordance with the impulses representing the units digits.
35. In a telephone exchange system, a plurality of lines designated by numerals

- comprising different tens and units digits, a connector switch for selecting any one of more than ten of said lines, an impulse device for controlling impulses representing tens and units digits of lines, and means for operating said connector under the control of said impulse device only in accordance with the impulses representing the units digits.
- 10 36. In a telephone exchange system, a plurality of lines designated by numerals representing different tens and units digits, a connector switch for selecting any one of one hundred of said lines, an impulse device for controlling impulses representing tens and units digits of lines, and means for operating said connector under the control of said impulse device only in accordance with the impulses representing the units digits.
- 15 37. In a telephone exchange system, a plurality of lines designated by numerals representing different tens and units digits, divided into numerical groups, a connector switch, an impulse device for controlling impulses representing tens and units digits of lines, separate means for operating said connector to select a certain group of said lines, and means responsive to the impulses representing the units digits to operate said connector to select a certain line in the selected group.
- 20 38. In a telephone exchange system, a plurality of calling and called lines designated by numbers comprising tens and units digits, means including a selector and a connector in series for connecting a calling line with any one of said called lines, an impulse device for producing impulses representing tens and units digits, means for operating said selector in accordance with the tens impulses representing the tens digit of a certain line, means for operating said connector in accordance with the units impulses representing the units digit of the said certain line, and means operative thereupon for connecting the calling line with the said certain line.
- 25 39. In a telephone exchange system, a plurality of calling and called lines designated by numbers comprising tens and units digits, means including a selector and a connector in series for connecting a calling line with any one of said called lines, an impulse device for producing impulses representing tens and units digits, means for operating said selector in one plane in accordance with the tens digit of a called line, means for operating said connector in the said plane in accordance with the units digit of the said called line, and means for operating said selector and connector in another plane.
- 30 40. In a telephone exchange system, a plurality of calling and called lines designated by numbers comprising tens and units digits, a selector and a connector, contacts of more than ten of said lines on said connector, a plurality of trunks, contacts of more than ten of said trunks on said selector, an impulse device for producing impulses representing tens and units digits, means for operating said selector in accordance with the tens digit of a called line, means for operating said selector to choose an idle one of said plurality of trunks, means for operating said connector in accordance with the units digit of the said called line, and means operative thereupon for connecting the calling line with the said called line through said selector, connector and a trunk.
- 35 41. In a telephone exchange system, a plurality of calling and called lines designated by numbers comprising tens and units digits, a plurality of trunks, a selector and a connector, contacts of one hundred of said lines on said connector, contacts of one hundred of said trunks on said selector, an impulse device for producing impulses representing tens and units digits, means for operating said selector in accordance with the tens digits of a called line, means actuated thereupon for operating said selector to choose an idle one of certain trunks, means for operating said connector in accordance with the units digit of the said called line, and means operative thereupon for connecting the calling line with the said called line through one of said ten trunks, said selector and said connector.
- 40 42. In a telephone exchange system, a plurality of calling and called lines designated by numbers comprising tens and units digits, a plurality of trunks, a selector and a connector, contacts of one hundred of said lines on said connector, contacts of one hundred of said trunks on said selector, an impulse device for producing impulses representing tens and units digits, means for operating said selector in accordance with the tens digit of a called line, means actuated thereupon for operating said selector to choose an idle one of a certain ten of said trunks, means for operating said connector in accordance with the choosing operation of said selector, means actuated thereupon for operating said connector in accordance with the units digit of said called line, and means operated thereupon for connecting the calling line with the said called line through one of said ten trunks, said selector and said connector.
- 45 43. In a telephone exchange system, a called line designated by a plurality of digits, a calling line, a first, second and third selectively operable switching device, means for connecting the calling line with the first device, means for operating the first device in accordance with two digits of the called line, means operative there-

- upon for connecting the calling line through the first device with the second device, means for operating the second device in accordance with the next digit of 5 the called line, means operative thereupon for connecting the calling line through the first and second devices with the third device, means for operating the third device in accordance with the last digit of the 10 called line, and means operative thereupon for connecting the calling line with the called line through said three devices. 44. In a telephone exchange system, a called line designated by a four digit number, a first selector, a second selector and a connector for establishing a connection with said line, and means for operating the first selector in accordance with the thousands and hundreds, the second selector in accordance with the tens and the connector in accordance with the units digits of the called line number. 45. In a telephone exchange system, a plurality of lines designated by numbers comprising thousands, hundreds, tens and units digits, an impulse device for producing impulses representing said digits, means including a first selector, a second selector and a connector in series for connecting a calling line with any one of said called lines, means for operating said first selector in accordance with the thousands and hundreds digit impulses produced by the device, means for operating the second selector in accordance with the tens digit impulses produced by the said device, and means for operating the connector in accordance with the units digit impulses produced by the said device. 46. In a telephone exchange system, a plurality of lines designated by numbers comprising thousands, hundreds, tens and units digits, an impulse device for producing impulses representing said digits, means including a first selector, a second selector, and a connector in series for connecting a calling line with any one of said called lines, means for operating said first selector in one plane in accordance with the thousands and in another plane in accordance with the hundreds digit impulses produced by the device, means for operating the second selector in the said other plane in accordance with the tens digit impulses produced by the said device, and means for operating the connector in the said other plane in accordance with the units digit impulses produced by the said device. 47. In a telephone exchange system, a plurality of lines designated by numbers comprising thousands, hundreds, tens and units digits, a plurality of trunks, an impulse device for producing impulses representing said digits, a first selector, a second selector and a connector, contacts of more than ten trunks on said first selector, contacts of more than ten other trunks on said second selector, contacts of more than ten lines on said connector, means for operating said first selector in accordance with the thousands and hundreds digit impulses of a called line, means for operating the second selector in accordance with the tens digit impulses of the said called line, means for operating the connector in accordance with the units digit impulses of the said called line, and means operative thereupon for connecting the calling line with the said called line. 48. In a telephone exchange system, a plurality of lines designated by numbers comprising thousands, hundreds, tens and units digits, a plurality of trunks divided into two groups, an impulse device for producing impulses representing said digits, a first selector, a second selector and a connector, contacts of one hundred trunks of one of said groups on said first selector, contacts of one hundred trunks of the other group on said second selector, contacts of one hundred lines on said connector, means for operating said first selector in accordance with the thousands and hundreds digit impulses of a called line, means actuated thereupon for operating the first selector to choose an idle one of said one of said groups of trunks, means for operating the second selector in accordance with the tens digit impulses of the said called line, means operative thereupon for actuating the second selector to choose an idle one of said other group of trunks, means for operating the connector in accordance with the units digit impulses of the said called line, and means operative thereupon for connecting the calling line with the said called line through a trunk of both groups, said first and second selectors and said connector. 49. In a telephone exchange system, a plurality of lines designated by numbers comprising thousands, hundreds, tens and units digits, a plurality of trunks divided into two groups, an impulse device for producing impulses representing said digits, a first selector, a second selector and a connector, contacts of one hundred trunks of one of said groups on said first selector, contacts of one hundred trunks of the other group on said second selector, contacts of one hundred lines on said connector, means for operating said first selector in accordance with the thousands and hundreds impulse digits of a called line, means actuated thereupon for operating the first selector to choose an idle one of ten of said one group of trunks, means for operating said second selector in accordance with the choosing operation of the first selector, means for operating the second selector in accordance with the tens digit impulses of the said called line, means operative thereupon for actuating said second selector.

5. In a telephone exchange system, a selector to choose an idle one of a certain ten of said other group of lines, means for operating the connector in accordance with the choosing operation of said second selector, 5 means operative thereupon for operating the connector in accordance with the units digit impulses of the said called line, and means actuated thereupon for connecting the calling line with the said called line through the 10 trunks chosen by the first and second selectors, said first and second selectors, and said connector.

50. In a telephone exchange system, a plurality of selectively operable switching devices, a plurality of differently designated lines, means for operating said devices in accordance with the designation of the wanted line, a plurality of trunks for each of said devices, means for operating said devices for choosing a trunk, and additional means for controlling the setting of said devices.

51. In a telephone exchange system, a selector switch, means for operating said switch to perform a primary and a secondary movement, a registering device, means for operating said registering device in accordance with the secondary movement of said selector, another selector switch, and 30 means for operating said other selector switch in accordance with the operation of the registering device.

52. In a telephone exchange system, a plurality of lines, means including a plurality 35 of selectively operable switching devices for interconnecting said lines, impulse controlling means for setting said devices, a variably operable mechanism, means for actuating said mechanism in accordance with the setting of one of said devices, and means controlled by said mechanism for variably controlling the setting of another device.

53. In a telephone exchange system, a plurality of selectively operable switching devices, a plurality of differently designated lines, means for operating said devices in accordance with the designation of wanted lines, a plurality of trunks for said devices, means for operating said devices for choosing a trunk, variably operable means for controlling the setting of said devices, and means controlled by the setting of a device for actuating said variably operable means.

54. In a telephone exchange system, a plurality of selectively operable switching devices, a plurality of differently designated lines, means for operating said devices in accordance with the designation of wanted lines, a plurality of trunks for each of said devices, means for operating said devices to choose a trunk, an electromagnetic mechanism, means responsive to the setting of any one of said devices for variably operating said mechanism, and means controlled by

said mechanism for variably controlling the 65 setting of said devices.

55. In a telephone exchange system, a plurality of differently designated lines, means including a plurality of selectively operable switching devices and a plurality of groups of trunks for interconnecting calling and called lines, a variably adjustable impulse controlling device, means responsive to the adjustment of said impulse controlling device for operating a switching device to select a group of trunks, and separate variably operable impulse controlling means for operating a switching device to 75 select a group of trunks.

56. In a telephone exchange system, a plurality of lines, means including a plurality of selectively operable switching devices and a plurality of groups of trunks for interconnecting calling and called lines, manually operable means for controlling a switching device to select a group of trunks, and automatically operable means for controlling a switching device to select a group of trunks.

57. In a telephone exchange system, a plurality of selectively operable means, a plurality of numerically designated telephone lines, manually adjustable means for producing impulses to control said selectively operable means in accordance with the designation of a called line, means responsive to such control for operating said devices to select the called line, means for rendering busy said lines, means responsive to the busy condition of a selected line for causing the selectively operable means to select and seize an idle line, a variably adjustable impulse producing means, means responsive to the adjustment of said last mentioned means for controlling switching means to select a line, and means for adjusting this impulse producing means to produce impulses representing the difference between the numerical value of the impulses produced by said manually adjustable means and that of the line seized by said selectively operable means.

58. In a telephone exchange system, a selector switch, a plurality of numerically designated telephone lines, an impulse sender operable in accordance with the designations of said lines, means responsive to the operation of said sender for operating said selector to select the designated line, means operated thereupon for causing said selector to select and seize another line, and automatic means for registering impulses the numerical value of which is equivalent to the difference between the numerical designation of the line first selected and that of the line seized.

59. In a telephone exchange system, a selector switch, movable and stationary con-

- 5 tacts for said switch, means for predeter-
mining a stationary contact to be engaged
by the movable contact, means for moving
the movable contact into engagement with
any stationary contact, including means for
moving the movable contact beyond the pre-
determined stationary contact, and a de-
vice for recording the number of stationary
contacts passed over by the movable con-
tact beyond the predetermined stationary
contact. 70
- 10 60. In a telephone exchange system, a se-
lector switch, movable and stationary con-
tacts for said switch, means for predeter-
mining a stationary contact to be engaged
by the movable contact, means for moving
the movable contact into engagement with
any stationary contact, including means for
moving the movable contact beyond the pre-
determined stationary contact, a device
for recording the number of contacts passed
over by the movable contact beyond the pre-
determined stationary contact, another se-
lector switch, and means for operating said
other switch in accordance with the oper-
ation of said device. 75
- 15 61. In a telephone exchange system, call-
ing and called lines designated by different
numbers, a plurality of selector switches,
means for operating any one of said
switches to perform two selective move-
ments, means for connecting the calling
line with a selector, means for controlling
the first selective movement of said selector
30 in accordance with an unknown variable
digit, and means for controlling the second
selective movement of said selector in ac-
cordance with a predetermined digit of the
called number. 80
- 20 62. In a telephone exchange system, a plu-
rality of lines, a plurality of trunks, a se-
ries of selectively operable switching de-
vices for interconnecting two lines by means
of said trunks, means for successively con-
trolling said devices to perform primary
and secondary selective operations, and
means for controlling the primary operation
45 of a succeeding device in accordance with
the secondary operation of a preceding de-
vice. 85
- 25 63. In a telephone exchange system, a plu-
rality of lines, a plurality of trunks, a se-
ries of selectively operable switching de-
vices for interconnecting two lines by means
50 of said trunks, means for successively con-
trolling the operation of said devices in ac-
cordance with the designation of the called
line, means for operating said devices to
choose a trunk, and means for controlling
60 the operation of a succeeding device in ac-
cordance with the trunk choosing operation
of a preceding device. 90
- 30 64. In a telephone exchange system, a plu-
rality of lines, a plurality of trunks, a se-
ries of selectively operable switching de-
vices for interconnecting two lines by means
of said trunks, means for successively con-
trolling the operation of said devices in ac-
cordance with the designation of the called
line, means for operating said devices to
choose an idle trunk, and means for control-
ing the operation of a succeeding device in
accordance with the trunk choosing operation
70 of a preceding device. 95
- 35 65. In a telephone exchange system, a plu-
rality of lines, a plurality of trunks, a se-
ries of selectively operable switching de-
vices for interconnecting two lines by means
of said trunks, means for successively con-
trolling the operation of said devices in ac-
cordance with the designation of the called
line, means for operating said devices to
choose an idle trunk, a variably operable
mechanism, means actuated during the trunk choosing
80 operation of all of said devices for actuating
said mechanism, and means responsive to the
setting of said mechanism for varying the
first mentioned operation of a succeeding
device in accordance with the trunk choosing
85 operation of a preceding device. 100
- 40 66. In a telephone exchange system, a plu-
rality of lines, a plurality of trunks, a se-
ries of selectively operable switching de-
vices for interconnecting two lines by means
of said trunks, means for successively con-
trolling the operation of said devices in ac-
cordance with the designation of the called
line, means for operating said devices to
choose a trunk, a variably operable mech-
anism, means actuated during the trunk choosing
90 operation of said devices for actuating
said mechanism, and means controlled by
said mechanism for varying the operation of
a succeeding device in accordance with the
trunk choosing operation of a preceding
100 device. 105
- 45 67. In a telephone exchange system, a plu-
rality of lines, a plurality of trunks, a se-
ries of selectively operable switching de-
vices for interconnecting two lines by means
of said trunks, means for successively con-
trolling the operation of said devices in ac-
cordance with the designation of the called
line, means for operating said devices to
choose a trunk, and means for controlling
110 the operation of a succeeding device in ac-
cordance with the trunk choosing operation
of a preceding device. 115
- 50 68. In a telephone exchange system, a plu-
rality of lines, a plurality of trunks, a se-
ries of selectively operable switching de-
vices for interconnecting two lines by means
of said trunks, means for successively con-
trolling the operation of said devices in ac-
cordance with the designation of the called
line, means for operating said devices to
choose an idle trunk, and means for control-
ing the operation of a succeeding device in
accordance with the trunk choosing operation
120 of a preceding device. 125
- 55 69. In a telephone exchange system, a plu-
rality of lines, a plurality of trunks, a se-
ries of selectively operable switching de-
vices for interconnecting two lines by means
of said trunks, means for successively con-
trolling the operation of said devices in ac-
cordance with the designation of the called
line, means for operating said devices to
choose an idle trunk, a variably operable
mechanism, means actuated during the trunk choosing
130 operation of all of said devices for actuating
said mechanism, and means responsive to the
setting of said mechanism for varying the
first mentioned operation of a succeeding
device in accordance with the trunk choosing
operation of a preceding device. 135

- tionary contacts passed over by the movable contact of each switch, and means controlled by said device for actuating the movable contacts of a succeeding switch in accordance with the operation of said device as controlled by the preceding selector switch.
69. In a telephone exchange system, a plurality of lines, a plurality of trunks, a plurality of selectively operable switching devices for interconnecting said lines, means for operating said devices in accordance with the designation of a called line, means including said devices for rendering busy said trunks, means dependent on the said operation of said devices for choosing an idle one of a certain number of said trunks, and means for controlling one device in accordance with the choosing operation of another device.
70. In a telephone exchange system, a plurality of lines, a plurality of trunks, a plurality of selectively operable switching devices for interconnecting said lines, means for operating said devices in accordance with the designation of a called line, means including said devices for rendering busy said trunks, means operable upon the said operation of said devices for choosing an idle one of a certain number of said trunks, and means for controlling one device prior to its said operation in accordance with the choosing operation of another device.
71. In a telephone exchange system, a plurality of differently designated lines, a plurality of trunks, a plurality of selectively operable switching devices for interconnecting said lines, means for operating said devices in accordance with the designation of a called line, means including said devices for rendering busy said trunks, means operable upon the said operation of said devices for choosing an idle one of a certain number of said trunks, an impulse register for controlling one device prior to its said operation, and means for actuating said register in accordance with the choosing operation of another device.
72. In a telephone exchange system, a plurality of differently designated lines, a plurality of trunks, a plurality of selectively operable switching devices for interconnecting said lines, means for moving said devices in accordance with the designation of a called line, means including said device for rendering busy said trunks, means dependent on the said moving of said devices for choosing an idle trunk, an impulse register for controlling the moving of one device in addition to its said moving, and means for actuating said register in accordance with the choosing operation of another device.
73. In a telephone exchange system, a plurality of selector switches, movable and stationary contacts for said switches, variably operable means for moving the movable con-
- tact of a switch into engagement with a certain stationary contact of the respective switch, means including said selector switches for rendering busy said stationary contacts, means for operating the movable contacts of the last mentioned switch to pass over all the busy stationary contacts of the respective switch, a device for registering the number of busy stationary contacts passed over by the movable contact, and means under the joint control of said variably operable means and said device for moving the movable contact of another switch into engagement with a certain stationary contact of said other switch.
74. In a telephone exchange system, a plurality of differently designated lines, a first selector, a second selector and a connector for connecting a calling line with a called line, a plurality of trunks accessible through said selectors, means for rendering busy said trunks, an impulse producing device, means for adjusting said device in accordance with the designation of the called line, means responsive to the adjustment of said device for operating the first selector to select a certain trunk, means for operating said first selector to choose an idle trunk, means for operating said second selector to choose an idle trunk, means under the joint control of the adjustment of said device and the trunk choosing operation of said first selector for operating the second selector to select a certain trunk, and means under the joint control of the trunk choosing operation of the second selector and the adjustment of said device for operating said connector to select a certain one of said lines.
75. In a telephone exchange system, a plurality of first selectors, second selectors and connectors, a plurality of differently designated lines, means for operating any first selector, second selector and connector in accordance with the designation of a called line, a registering device associated with each first selector, a plurality of trunks for connecting said first selectors with said second selectors, a plurality of trunks for connecting said second selectors with said connectors, means for operating said selectors to cause each selector to choose a trunk, means for operating a registering device in accordance with the choosing operations of its associated first selector and the connected second selector, and means for operating the connected second selector and connector in accordance with the operations of the registering device.
76. In a telephone exchange system, a plurality of first selectors, second selectors and connectors, a plurality of differently designated lines, means for operating any first selector, second selector and connector in accordance with the designation of a called line, a registering device associated with each

- first selector, a plurality of trunks for connecting said first selectors with said second selectors, a plurality of trunks for connecting said second selectors with said connectors, 5 means for operating said selectors to cause each selector to choose a trunk, means for operating a registering device in accordance with the choosing operation of its associated first selector, means for operating a second 10 selector in accordance with the operation of the last mentioned registering device, means for operating this registering device in accordance with the trunk choosing operation of the last mentioned second selector, means 15 for operating the connector connected with the last mentioned second selector in accordance with the second selector controlled operation of the last mentioned registering device.
- 20 77. In a telephone exchange system, a plurality of first selectors, second selectors and connectors, a plurality of differently designated lines, means for operating any first selector, second selector and connector 25 in accordance with the designation of a called line, a registering device associated with each first selector, a plurality of trunks for connecting said first selectors with said second selectors, a plurality of trunks for 30 connecting said second selectors with said connectors, means for operating said selectors to cause each selector to choose a trunk, means for operating a registering device in accordance with the choosing operation 35 of its associated first selector, means for operating a second selector prior to its operation in accordance with the designation of the called line, in accordance with the operation of the last mentioned registering device, means for operating this registering 40 device in accordance with the trunk choosing operation of the last mentioned second selector, and means for operating a connector connected with the last mentioned second selector in accordance with the last mentioned second selector controlled operation 45 of the last mentioned registering device, prior to the operation of said connector in accordance with the designation of the wanted line.
- 50 78. In a telephone exchange system, a plurality of differently designated lines, means including a plurality of selectors and a plurality of other selectors for interconnecting calling and called lines, movable and a plurality of differently designated stationary contacts for said selectors, the stationary contacts of each of the said other selectors being arranged in a different order, 55 a plurality of correspondingly designated trunks terminating on the corresponding stationary contacts of the said other selectors, and a plurality of trunks, each terminating at one end in the movable contact of one of the said other selectors, and a 60 different stationary contact of one of the first mentioned selectors.
79. In a telephone exchange system, a plurality of switching devices, trunk terminals, and cooperating movable contacts for 70 each of said devices, a plurality of connecting means, differently designated contacts on said connecting means, a trunk, multiple connections from one end of said trunk to certain correspondingly designated contacts 75 of a group of said connecting means, a connection from the other end of said trunk to the movable contact of a certain switching device, another trunk, multiple connections from end of said other trunk to certain other correspondingly designated contacts of another group of connecting means including some of said mentioned group, and a connection from the other end of said other trunk to the movable contact of a certain other switching device. 80
80. In a telephone exchange system, a plurality of switching devices, a series of trunk terminals for each of said devices, the first terminal in each of said devices 85 bearing a different designation, a plurality of connecting means, differently designated contacts on said connecting means, a trunk, multiple connections from one end of said trunk to correspondingly designated contacts 90 of said connecting means, and to a device the first trunk terminal of which bears the designation corresponding to that of the last mentioned multiplied contacts, another 95 trunk, and multiple connections from said other trunk to other correspondingly designated contacts of said connecting means and to a device the first terminal of which bears a designation corresponding to that of the last mentioned multiplied terminals. 100
81. In a telephone exchange system, a group of switching devices, another group of switching devices, trunk terminals, a plurality of connecting means, differently designated contacts on said connecting means, 110 a trunk, multiple connections from one end of said trunk to certain correspondingly designated contacts of a group of said connecting means, a connection from the other end of said trunk to the movable contact of a certain switching device in the first mentioned group, another trunk, multiple connections from end of said other trunk to certain correspondingly designated contacts of another group of connecting means, and a connection from the other end of said other trunk to the movable contact of a certain switching device of said other group. 115
82. In a telephone exchange system, a group of switching devices, another group of switching devices, a series of trunk terminals for each of said devices, the first terminal in each of said devices of the first mentioned group bearing a different designation and the first terminal of each of the 120 125 130

- devices in the second group bearing a designation corresponding to that of a first terminal of a device in the first group, a plurality of connecting means, differently 5 designated contacts on said connecting means, a trunk, multiple connections from one end of said trunk to correspondingly designated contacts of a group of connecting means and to a device of the first mentioned group the first trunk terminal of which bears the designation corresponding to that of the last mentioned multiplied contacts, another trunk, and multiple connections from said other trunk to correspondingly designated contacts of another group of connecting means and to a device of the other group the first terminal of which bears a designation corresponding to that of the last mentioned multiplied terminals. 10
83. In a telephone exchange system, a group of switching devices, another group of switching devices, trunk terminals and co-operating movable contacts for each of said devices, a plurality of connecting means, differently 15 designated contacts on said connecting means, a trunk, multiple connections from one end of said trunk to certain correspondingly designated contacts of a group of said connecting means, a connection from the other end of said trunk to the movable contact of a certain switching device in the first mentioned group, another trunk, multiple connections from one end of said other trunk to certain correspondingly designated contacts of another group of connecting means, a connection from the other end of said other trunk to the movable contact of a certain switching device of said other group, a third trunk, multiple connections from one end of said third trunk to certain other correspondingly designated contacts of a plurality of connecting means including some of both said groups, a connection from the other end of said third trunk to the movable contact of a certain other device in said first mentioned group, a fourth trunk, multiple connections from one end of said fourth trunk to certain other correspondingly designated contacts of a plurality of connecting means including the remainder of said other group, and a connection from the other end of said fourth trunk to the movable contact of a certain other switching device in said other group. 20
84. In a telephone exchange system, a switching device, another switching device, a plurality of trunks accessible in a certain order to said first mentioned switching device and in a different order to said other switching device, a plurality of connecting means, differently 25 designated contacts on said connecting means, a trunk multiple connection from one end of said trunk to a contact of a connecting means and correspondingly designated contacts of other connecting means, a connection from the other end of said trunk to said first mentioned device, another trunk, a multiple connection from one end of said other trunk to another contact of a connecting means and to correspondingly numbered contacts of other connecting means, and a connection from the other end of the last mentioned trunk to the said other switching device. 70
85. In a telephone exchange system, a group of switching devices, another group of switching devices, differently designated trunk terminals arranged in overlapping groups of equal size on the devices of the first mentioned group and in corresponding- 75 ly overlapping groups of equal size on the devices of the other group, movable contacts for each device arranged to cooperate with the trunk terminals of the respective device, a plurality of connecting means, differently 80 designated contacts on said connecting means, a trunk, multiple connections from one end of said trunk to certain correspondingly designated contacts of a group of said connecting means, a connection from the other end of said trunk to the movable contact of a certain switching device in the first mentioned group, another trunk, multiple connections from one end of said other trunk to certain correspondingly designated contacts of another group of connecting means, a connection from the other end of said other trunk to the movable contact of a certain switching device of said other group, a third trunk, multiple connections from one end of said third trunk to certain other correspondingly designated contacts of a plurality of connecting means including some of both said groups, a connection from the other end of said third trunk to the movable contact of a certain other device in said first mentioned group, a fourth trunk, multiple connections from one end of said fourth trunk to certain other correspondingly designated contacts of a plurality of connecting means including the remainder of said other group, and a connection from the other end of said fourth trunk to the movable contact of a certain other switching device in said other group. 90
86. In a telephone exchange system, a group of switching devices, another group of switching devices, a series of stationary trunk terminals and co-operating movable contacts for each of said devices, the first terminal in each of said devices of the first mentioned group bearing a different designation, and the first terminal of each of the devices in the second group bearing a designation corresponding to that of a first terminal of a device in the first group, a plurality of connecting means, differently 95 designated contacts on said connecting means, a trunk, multiple connections from one end of said trunk to correspondingly 100

- designated contacts of a group of connecting means, and to the movable contact of a device of the first mentioned group the first trunk terminal of which bears the designation corresponding to that of the last mentioned multipled contacts, another trunk, multiple connections from said other trunk to correspondingly designated contacts of another group of connecting means and 5 the movable contact of a device of the other group the first terminal of which bears a designation corresponding to that of the last mentioned contacts, a third trunk, multiple connections from said third trunk to other 10 correspondingly designated contacts of a plurality of connecting means including some of both said groups, and to the movable contact of a device of the first mentioned group the first terminal of which 15 bears a designation corresponding to that of the last mentioned multipled contacts, a fourth trunk, and multiple connections from said fourth trunk to other correspondingly designated contacts of a plurality of 20 connecting means including the remainder of said other group, and to the movable contact of a device of the other group the first terminal of which bears a designation corresponding to that of the last mentioned 25 multipled contacts.
87. In a telephone exchange system, a plurality of second selectors divided into groups, a bank of trunk terminals for each second selector, each terminal bank being 30 differently numbered from those within the same group and each of the banks containing terminals of trunks appearing in the banks of the other second selectors within the same group, a movable contact for each 35 second selector, a plurality of first selectors, a bank of trunk terminals for each first selector, the designation of each terminal being different from that of the other terminals within the same bank, and multiple 40 connections to as many correspondingly numbered first selector terminals as there are like numbered second selector banks and to the movable contacts of such second selectors.
88. In a telephone exchange system, a plurality of switching devices, a differently numbered bank of line terminals for each device, each bank containing terminals of lines appearing in a plurality of other 45 banks, a movable contact for each device, a plurality of selectors divided into groups, a terminal bank for each selector, each terminal bank being differently numbered from those within the same group and each 50 of the banks containing terminals of lines appearing in the banks of the other selectors within the same group, and multiple connections between the correspondingly numbered terminals of all the selectors and the movable contact of the device the first
- terminal of which is designated like the multipled terminals of the selectors.
89. In a telephone exchange system, a plurality of connectors, a differently numbered bank of line terminals for each connector, each bank containing terminals of lines appearing in a plurality of other banks, a movable contact for each connector, a plurality of second selectors divided into groups, a terminal bank for each second selector, each terminal bank being differently numbered from those within the same group and each of the banks containing terminals of trunks appearing in the banks of the other second selectors within the same 70 group, and multiple connections between the correspondingly numbered terminals of all the second selectors and the movable contact of the connector the first terminal of which is designated like the multipled terminals of the second selectors.
90. In a telephone exchange system, a plurality of switching devices, a differently numbered bank of line terminals for each device, each bank containing terminals of lines appearing in a plurality of other banks, a movable contact for each device, a plurality of selectors divided into groups, a terminal bank for each selector, each terminal bank being differently numbered from those within the same group and each of the banks containing terminals of lines appearing in the banks of the other selectors within the same group, multiple connections between the correspondingly numbered terminals of all the selectors and the movable contact of the device the first terminal of which is designated like the multipled terminals of the selectors, a movable contact for each selector, a plurality of connecting means, a terminal bank for each connecting means, the designation of each terminal being different from that of the other terminals within the same bank, multiple connections to as many correspondingly numbered connecting means as there are like numbered selector banks, and to the movable contacts of such selectors, a plurality of telephone lines connected to the terminals of the devices, means for connecting a calling line with the movable contacts of a connecting means, and means for selectively operating said devices, selectors and connecting means.
91. In a telephone exchange system, a plurality of connectors, a differently numbered bank of line terminals for each connector, each bank containing terminals of lines appearing in a plurality of other banks, a movable contact for each connector, a plurality of second selectors divided into groups, a terminal bank for each second selector, each terminal bank being differently numbered from those within the same group and each of the banks containing ter-

minals of trunks appearing in the banks of the other second selectors within the same group, multiple connections between the correspondingly numbered terminals of 5 all the second selectors and the movable contact of the connector the first terminal of which is designated like the multiplied terminals of the second selectors, a movable contact for each second selector, a plurality 10 of first selectors, a terminal bank for each first selector, the designation of each terminal being different from that of the other terminals within the same bank, multiple connections to as many correspondingly 15 numbered first selector terminals as there are like numbered second selector banks, and to the movable contacts of such second selectors, a plurality of telephone lines connected to the terminals of the connectors, 20 means for connecting a calling line with the movable contacts of first selectors, and means for selectively operating said selectors and connectors.

92. In a telephone exchange system, a 25 plurality of final selector switches, movable contacts for said switches having a definite normal position, trunk lines terminating in said movable contacts, a plurality of stationary contacts for said switches, means 30 for actuating the movable contacts of a switch to cooperate with the associated stationary contacts, and a plurality of subscribers' lines each connected to a contact in a number of said switches, the contact of 35 one subscriber's line occupying in each switch a different position relative to the normal position of the movable contacts.

93. In a telephone exchange system, a 40 plurality of final selector switches, wipers for said switches having a definite normal position, trunk lines terminating in said wipers, a plurality of contacts in said switches, means for actuating the wipers to 45 cooperate with the contacts, a subscriber's line, a connection from said line to a contact of one of said switches having a certain position relative to the normal position of the wipers, and a connection from said line to a contact of another switch 50 having a certain other position relative to the normal position of the wipers.

94. In a telephone exchange system, a 55 plurality of subscribers' lines, a plurality of final selector switches, a movable contact for each of said switches having a definite normal position, one fixed contact in each of said switches in a different location relative to the normal position of the movable contact, and connections from all of said 60 fixed contacts to a subscriber's line.

95. In a telephone exchange system, a 65 plurality of connectors, and a plurality of subscribers' lines, one line appearing in each connector on a different position.

96. In a telephone exchange system, a

plurality of subscribers' lines, a plurality of connectors, means for operating said connectors to perform primary and secondary movements, means responsive to a certain primary and a certain secondary movement 70 of a connector for selecting a certain line, and means responsive to a certain other primary and said certain secondary movement of another connector for selecting the said certain line. 75

97. In a telephone exchange system, a plurality of subscribers' lines, a plurality of connectors, and means for operating said connectors by primary and secondary movements, each connector selecting the same 80 line in response to a different number of primary steps and the same number of secondary steps.

98. The method of establishing connections in machine switching telephone exchange systems, consisting of the following 85 switching operations; first, setting a selector in accordance with the designation of the called line to select a trunk through which normally access may be had to the called line, second, if this trunk is barred operating the selector to select another trunk through which normally access is had to another line, and third, operating the succeeding selector to correct the setting of 90 the previous selector. 95

99. The method of establishing connections in machine switching telephone exchange systems which consists in performing in one section of the connection selective operations in accordance with the designation of the called line or in accordance with the designation of another than the called line, and eliminating in another section of the connection the difference between 100 the desired and the actually performed selective operations. 105

100. A telephone exchange system comprising selector terminal banks to which lines, each numerically designated in accordance with the access it gives, are connected in the following manner: each line is connected to a relatively different terminal of 110 each selector bank.

101. A telephone exchange system comprising subscribers' lines and connector banks and wired in the following manner; each subscriber's line is connected to the terminal banks of a plurality of connector switches, and each in a different position in 115 each bank. 120

102. A telephone exchange system comprising subscribers' lines and connector banks and wired in the following manner; each subscriber's line is connected in the 125 banks of a plurality of connector switches, in the same horizontal row in each bank but in a different vertical row in each bank.

103. A telephone exchange system comprising subscribers' lines and connector 130

banks and wired in the following manner; each subscriber's line is connected to a different primary but to the same secondary group of contacts in each one of a plurality of connector banks.

104. A telephone exchange system comprising trunks and selector banks wired in

the following manner; each trunk is connected to a different primary but to the same group of secondary contacts in each one of a plurality of selector banks.

In witness whereof, I hereunto subscribe my name this first day of May, A. D. 1920.

ARTHUR H. ADAMS.
